[57]

ABSTRACT

The machine disclosed herein is known as a high velocity impact forming machine. It is provided with two tooling or anvil members and associated equipment assembled in such manner that no multiple pounding or restrike results as the machine is used. The machine has adjusting means for adjusting the energy output from stroke-to-stroke, thus enabling the user to use a sequence of varying energy forming steps such as breaking scale in hot work, preforming, and blocking. Means is provided by which the tooling is separated immediately after forming so that handling of the formed parts can commence immediately and without pause. Operation cycle time is thus used most efficiently. The structure of the machine is such that relatively low and fully controllable foundation loadings result. The machine can be provided with sufficient die area to accommodate multiple cavity tooling and is provided with means to sustain eccentric loadings from off center work. The machine is capable of stroking when the tooling and workpiece are absent without any dilatorius effects on the machine. The machine has completely adjustable tooling daylight from stroke-to-stroke.

HIGH ENERGY FORGING PRESS

REFERENCE TO RELATED APPLICATION

This application is a continuation-in-part of patent application, Ser. No. 886,130, filed Dec. 18, 1969, now abandoned.

PRIOR ART

Previous machines of this type work on the counter-blow principle in which anvil members are driven together by the sudden release of a high pressure gas spring. Machines in this art have a number of significant advantages over conventional mechanical and hydraulic forging presses. One is that for their size and cost, they are capable of very high forming or coining loads. Also, as with hydraulic presses, the forming load is independent of stroke, the point of maximum load may be anywhere from the beginning to the end of forming.

Tool closing velocities are in a range well above those of mechanical presses and hammers. There is evidence that many materials, especially the super-alloys, are more ductile at these higher forming velocities. That is, at higher deformation rates, these metals endure a higher percentage of deformation before fracturing. The greater forming speed is also advantageous in hot forging. The workpiece surface does not have time to cool as it moves into the die. Recrystallization heat is maintained and the metal surface does not work harden. The workpiece can be moved farther and into smaller sections with little or no draft.

Because the pressure and volumetric expansion of the gas spring can be accurately controlled, these machines are extremely repeatable. The exact same amount of energy can be delivered to workpiece after workpiece. Dimensional tolerances can be kept very tight.

The combined effects of high tonnage and velocity, and repeatability permit the forming of flash free precision forgings in a single closed die cavity. Considerable savings are to be had in initial billet weight and in machining after forging. In some cases heretofore unforgeable geometries can be obtained.

The previous machines of this type, however, have various undesirable features. Dies and tooling members are subjected to severe multiple pounding or restrike. During a stroke, the counterblow members alternately rebound from each other and impact together again under the thrust of the gas spring. For each forming, rapid pounding persists until all excess energy has dissipated. The condition is particularly bad when forming flat workpieces which create high loads. A small percentage of the energy goes into deforming the piece, while a large percentage of the energy is stored elastically in the tooling at each blow. The number of times the tooling is shock loaded is a large multiple of the number of pieces produced by the machine, and early die fatigue is invited.

This bounce or restrike is particularly distressing in hot work using liquid carried lubricants. After the first blow the carrier in contact with the hot workpiece has vaporized and blown off. During succeeding restrikes the workpiece movement is essentially unlubricated and high erosive.

Another common feature of the previous machines of this type is that after forming the dies open or separate very slowly at a rate much lower than their closing

speed and generally slower than conventional hammers or mechanical presses. The anvil members are reset back to stroking position by slow-acting hydraulic pistons. This step imposes a delay in the production cycle of the machine because the operator must wait until the tooling has cleared before unloading the part.

The slow rate of tooling separation also means that in hot forming, the workpiece must be in contact with the die for periods of a second or more. Thus the die surfaces must endure an intense heating cycle after each forming, and premature heat checking results. Often parts will contract and stick to the punch before the punch clears, resulting in permanent damage to that member.

In general, previous machines of this type have been designed to forge parts solely in a single blow. Die area has been limited to that sufficient for a single die cavity. In some cases, energy output is fixed, the intensity of the blow cannot be varied as it can, for instance, with a steam hammer. Such common practice die-saving procedures as breaking scale, preforming, fullering, edging, and blocking have been ruled out. The process thus far has been limited to symmetrical parts which must be completed on one blow.

High die pressures and extreme washout and erosion are inherent when deforming metal in a single blow from simple stock shapes into finishing dies of complex geometry. The logical choice of tool steels under these circumstances are those with the highest hardness and wear resistance. However, such selection has been ruled out for previous machines of this type because of the severe shock and thermal conditions they impose on tooling. Softer impact and heat check resistant steels must be used with the result that dies erode and wash out at a rapid rate making long production runs quite uneconomical.

OBJECTS OF THE INVENTION

It is, accordingly, an object of the invention to provide a high velocity impact forming machine which preserves the advantages while embodying many improvements over previous machines of this type.

Another object of the invention is to provide a forming machine that is simple in construction, economical to manufacture, and simple and efficient to use.

Another object of the invention is to provide a machine which operates in a manner conducive to good die life and economical production of parts.

Another object of the invention is to provide a forming machine capable of very high coining loads with relatively low and fully controllable foundation loading.

Another object of the invention is to provide a forming machine with means to separate the tooling at a very high speed immediately after each forming stroke.

Another object of the invention is to provide a machine which strikes a single blow at a time without multiple pounding or restrike.

Another object of the invention is to provide a forming machine having an especially large die area.

Another object of the invention is to provide a machine that is capable of stroking when a workpiece or the die itself is absent without self-destruction.

Another object of the invention is to provide a forming machine having a completely adjustable energy output from stroke to stroke.

Another object of the invention is to provide a forming machine having a completely adjustable stroke and

completely adjustable tooling daylight from stroke to stroke.

Another object of the invention is to provide a forming machine which can perform work such as shearing, trimming, and punching.

Another object of the invention is to provide a high velocity impact forming machine in which means is provided to accommodate reasonable eccentric forming loads without unduly stressing the machine.

DESCRIPTION OF THE DRAWINGS

FIG. 1 is a front view of the first embodiment of the machine with a portion cross sectioned to better illustrate the invention;

FIG. 2 is a longitudinal cross sectional view of the first embodiment machine with fluid lines shown partly in schematic;

FIG. 3 is a sectional view of the primary piston chamber of the first embodiment illustrating details of construction;

FIG. 4 illustrates reset seal means used in the first embodiment machine;

FIG. 5 illustrates check valve means used in the first embodiment machine;

FIG. 6 is a sectional view of the secondary piston chamber of the first embodiment machine illustrating details of construction;

FIG. 7 shows the sequential position of the various parts of the first embodiment machine during a working cycle;

FIG. 8 shows the machine members along mathematically plotted curves relating their strokes to time for a high tonnage coining operation;

FIG. 9 is a diagram showing the relative positions of the first and second tooling members with respect to time; it is an illustration similar to FIG. 7 showing the first embodiment machine during a low tonnage deep forming stroke operation;

FIG. 10 shows mathematically plotted curves of the primary piston chamber thrust as the first tooling member strokes;

FIG. 11 is a front view of the second embodiment of the invention with portions cross sectioned;

FIG. 12 is a side view of the second embodiment machine with portions cross sectioned to better illustrate its arrangement;

FIG. 13 is a front view of the third embodiment of the invention with portions cross sectioned to illustrate its working parts;

FIG. 14 is a cross sectional view of a fourth modification at the lower portion of the machine;

FIG. 15 is a cross sectional view of a fifth arrangement of the machine.

DETAILED DESCRIPTION OF THE DRAWINGS

In this invention, the self-reaction principle of the previous counterblow type machines has been abandoned in favor of the kind of impact one sees on a pool table. One ball is propelled towards a second ball which is at rest. Upon impact, the first ball stops, while its velocity is transferred to the second ball which in turn speeds away. In this invention, the first or upper tooling member accelerates downward toward the second or lower die supporting member which is suspended at rest. Upon contact, a workpiece is forged due to the inertia of the two impacting members. The first tooling member stops, and the second tooling member moves

downward propelled by kinetic energy imparted to it during the impact. The effect is an immediate opening of the die after forming. The die opening speed is in the same range as that of the upper tooling approach speed. No pounding or restrike occurs. The punch tooling moves into the die for a single forming blow followed by immediate retreat of the lower tooling, all in an interval of milli-seconds.

The essential components of this invention are the two tool supporting members, a common frame assembly which guides these tooling members in vertical alignment, a primary piston chamber to actuate the first tooling member, and a secondary piston chamber with fluid controls to yieldably suspend the second tooling member in position for forming. Upon signal, the primary piston chamber is capable of instantaneously exerting a large gas pressure thrust, accelerating the first tooling member toward the second tooling member. This primary chamber also incorporates primary stopping means capable of exerting a counter

thrust on the first tooling member if that member moves past a certain limiting point thereby stopping first tooling member motion toward the second tooling member. Reset means recompress primary pressure gas in the primary chamber means and removes the first tooling member to a position from which it can be stroked again. The primary chamber is attached fixed to the frame assembly. The frame in turn can be anchored rigidly to a fixed foundation or flexibly suspended by a gas spring or other means. Therefore, reaction for the first tooling member acceleration and stopping thrusts is taken either by the foundation through a stationary frame or inertially by a suspended frame.

The secondary chamber suspends the second tooling member in up position ready for forming with just sufficient force to balance the second tooling member weight. When impact propels the second tooling member downward, integral fluid controls permit the secondary piston chamber to yield and offer negligible resistance to motion until the tooling has adequately opened, after which the secondary chamber means then cushions and decelerates the second tooling member to a rapid stop. After the operator has unloaded the die and reloaded a billet, he signals the fluid controls and the secondary chamber means raises the second tooling member again to its forming position. The secondary piston chamber may itself be supported by a fixed foundation or by a suspended machine frame assembly. Therefore, reaction for stopping the second tooling member may be taken either by the foundation or inertially by a suspended machine frame.

First Embodiment

Referring to FIG. 1, in the first embodiment of this invention, the frame is shown attached rigidly to the foundation. As will be seen, the primary piston chamber in this embodiment incorporates a unique primary stopping means which permits maximum kinetic energy output and absorption with minimum thrust and counterthrust reaction peaks being taken through the stationary frame to the foundation. The secondary chamber in this arrangement is shown supported directly on the foundation.

The external fluid circuitry shown in FIG. 2 aids in the discussion of the machine operations and the functions which external fluid controls must perform in

conjunction with the machine. The invention is not, however, limited to the particular circuitry shown, since a variety of pump and control valve arrangements can be used to perform the necessary functions.

Referring to FIG. 3, the first embodiment primary chamber is constructed in the following manner. Shaft closure plate 11 is supported on the upper ends of side frames 80 and is clamped thereto by means of bolts 84. Closure plate 11 supports the lower ends of outer cylinder 13 and large inner cylinder 14. Small inner cylinder 15 is received inside of large inner cylinder 14 and small cylinder 15 is supported by the upper end of large cylinder 14. Head closure plate 12 rests on the upper ends of outer cylinder 13 and small cylinder 15. Cylinders 13, 14, and 15 are all disposed concentric to each other and are clamped in position between closure plates 11 and 12 by means of tie rods 18 and nuts 19. Seal means 34 between cylinder 13 and lower plate 11 and seal means 35 between cylinder 13 and upper plate 12 prevent communication between the interior and exterior of outer cylinder 13.

Hydraulic cylinder 17 is supported on head closure plate 12 and is received in the counterbore as shown. Hydraulic head cap 16 rests on top of cylinder 17 and cylinder 17 is clamped in position between closure plate 12 and head cap 16 by means of tie rods 20 and nuts 21. Seal means 37 between cylinder 17 and head cap 16 prevents communication between the interior and exterior of cylinder 17.

Shaft closure plate 11 has an opening concentric to cylinder 13 which permits the primary shaft 3 of the first tooling member to reciprocate vertically in and out of the primary chamber assembly. Bushing 25 located in this opening surrounds the primary shaft and is held in position by bolted retaining plate 26. Bushing 25 provides an appropriate wear surface for primary shaft 3 to reciprocate against. Seal means 27 prevents communication between the interior and exterior of the assembly through the shaft opening in closure plate 11. Primary piston head 4 is attached to screwing or other means to primary shaft 3. The outside diameter of piston head 4 is in sealed reciprocating contact with the bore of small inner cylinder 15. The stroke of the first tooling member and length of small cylinder 15 are disposed to insure that seal means 28 never moves out from the bore of cylinder 15.

Collar piston 6 surrounds and is in sealed reciprocating contact with primary shaft 3. The collar piston outside diameter is in sealed reciprocating contact with the lower inside wall of large inner cylinder 14. The vertical stroke of collar piston 6 is limited on top by the bottom of small inner cylinder 15 and at the bottom by shaft closure plate 11.

Fluid replenishment piston 7 is a ring shaped member which surrounds and is in sealed reciprocating contact with the outside wall of small cylinder 15. The replenishment piston outside diameter is in sealed reciprocating contact with the upper inside bore of large cylinder 14. The vertical stroke of replenishment piston 7 is limited on top by a step to greater wall diameter in cylinder 15. Piston 7 is limited at the bottom of its stroke by check seat 9.

Check seat 9 and check plate 8 just below it form an annular check valve at the bottom of small inner cylinder 15. Check seat 9 is a ring shaped member which is slotted radially outward as shown in FIG. 5 and is clamped in position between a step in the wall of cylinder

15 and a step in the bore of large cylinder 14. Check plate 8 is a plate cut in the shape of a ring and is also slotted radially outward. Check plate 8 has a very short vertical stroke between check seat 9 on top and a step in the bore of cylinder 14 below. Plate 8 and seat 9 are oriented so that if plate 8 is up against seat 9, the slots in each plate are covered by the other plate. Communication or flow upwards is self-restricting because it seats check plate 8, closing the slots. Downward communication is unrestricted because it moves plate 8 down from seat 9, opening the slots. Slotting after this fashion gives the check valve a large orifice with a very short opening stroke.

Head closure plate 12 has an opening concentric to outer cylinder 13 through which opposed reset piston 5 reciprocates. Bushing 22 is located in this opening and surrounds opposed piston 5. This bushing provides an appropriate wear surface for opposed piston 5 piston reciprocate against. Bushing 22 is clamped in place by hydraulic cylinder 17. Seal means 33 prevents communication around the opposed reset piston between, above and below bushing 22. Seal means 38 prevents communication between the interior and exterior of cylinder 17 and seal means 39 prevents communication to the exterior of the chamber between bushing 22 and closure plate 12. The upper end of the opposed reset piston is flanged intermittently about its diameter. This flange is in reciprocating contact with the bore of cylinder 17. The opposed piston can travel downward until its upper flange contacts bushing 22. The opposed piston can travel upward until it contacts hydraulic head cap 16. Hydraulic cylinder 17 and head cap 16 comprise a hydraulic actuation chamber for opposed reset piston 5.

Face flange 23 is attached by screwing or other means to the lower end of opposed piston 5. Face flange 23 carries a radial reset seal ring 10 of resilient composition and is designed to sealingly enter into engagement with the upper face of primary piston head 4. Pressure control sleeve 24 fits in an eccentrically located hole through primary piston head 4. In sealed engagement with the primary piston head and primary piston shaft, sleeve 24 provides pressure communication between the upper face of the piston head and drillings in the first tooling member which lead to hose connection 44 and external depressurization and stroke control valves. Sleeve 24 also locks primary piston head 4 from unscrewing from the primary shaft.

Diameter N of primary shaft 3 is less than diameter P of opposed piston 5. Diameter R of primary piston head 4 is greater than diameter Q of face flange 23. The outside diameter of collar piston 6 is greater than diameter R.

Region A is confined between closure plates 11 and 12. Region A communicates around primary piston shaft 3 below collar piston 6 and through porting slots at the bottom of inner cylinder 14 into the annular space between cylinders 14 and 13 and through porting slots at the top of small inner cylinder 15 into the space above primary piston head 4 and below and around the portion of the opposed piston 5 exposed below head closure plate 12. Region A confines the primary pressure gas which is compressed by the reset system to store energy and released by stroke initiation means to impart that energy in first tooling member stroking motion. A constant quantity of primary pressure gas is maintained in region A by means of valve V12.

Intermediate region C is confined by the lower end of primary piston head 4, collar piston 6, the under surface of check valve plates 8 and 9, the lower bore portion of large inner cylinder 14 and the inside wall of small inner cylinder 15. Intermediate region C is filled with hydraulic fluid which functions in the stopping and limiting of first tooling member stroking motion. Two spigots 42 provide communication between intermediate region C and the external hydraulic circuit. Region D is confined by the upper surface of check valve plates 8 and 9, the upper bore portion of inner cylinder 14, the outer surface of small cylinder 15, and the under-surface of replenishment piston 7. Region D is also filled with hydraulic fluid. The total volume of hydraulic fluid in intermediate region C and replenishment region D is left constant during operation; filling and bleeding the regions is accomplished by valves V9 and V10. The upper face of collar piston 6 is recessed CC for hydraulically cushioned engagement with primary piston head 1, when the first tooling member down stroke is being stopped; intermediate region C fluid acts as the cushioning medium when the two members enter male-female engagement.

Region F is confined by the upper end of cylinder 15, the upper bore portion of cylinder 14 and the top of fluid replenishment piston 7. Seal means 36 between inner cylinders 14 and 15 prevents communication with region A primary pressure gas. Drilled holes and piping 46 communicate region F with external fill and bleed valves 15 and 16. A fixed quantity of pressure gas is maintained in region F during operation, the pressure being limited to approximately one fourth that of the primary pressure gas confined in region A.

Region E is the hydraulic chamber confined by opposed piston 5, cylinder 17, bushing 22 and head cap 16. It is filled with hydraulic fluid and communicates with the external hydraulic power system through porting means 41 in head cap 16.

The secondary piston chamber shown in FIG. 6 is arranged surrounded by an annular accumulator fluid control means. Chamber closure plate 56 rests on and is suitably anchored to the foundation. The lower ends of outer and inner accumulator cylinders 59 and 58 and chamber cylinder 57 rest on closure plate 56. Upper plate 55 rests on the upper ends of outer cylinder 59 and inner cylinder 58. Upper plate 55 has an opening through which chamber cylinder 57 extends upward. Upper plate 55 rests on a step in the outer wall of chamber cylinder 57. Accumulator cylinders 58 and 59 and chamber cylinder 57 are all disposed concentric to each other and are clamped in position between upper plate 55 and closure plate 56 by tie rods 70 and nuts 71. Seal means 65 and 66 prevent communication between the interior and exterior of cylinder 59. Seal means 68 and 69 prevent communication between the interior and exterior of cylinder 58. Seal means 67 prevents communication between the interior and exterior of the assembly at the opening in upper plate 55. A circular recess in closure plate 56 receives the lower end of chamber cylinder 57 in fitted engagement, restricting communication between the inside and outside of cylinder 57 at its lower end.

The upper end of chamber cylinder 57 has an entrance through which secondary piston 50 is permitted vertical reciprocating motion in and out of the assembly. Bushing 60 located in this entrance surrounds piston 50 and is held in place by bolted retaining plate 61.

Bushing 60 provides an appropriate wear surface for piston 50 to reciprocate against. Seal means 62 prevents communication with the exterior of the chamber through the piston entrance. As shown, piston 50 is flanged 51 at its interior end. Piston 50 can stroke upwards until its flange 51 contacts the piston entrance and stroke downward until it contacts check plate 54 resting on closure plate 56.

Check plate 54 covers a drilled port in closure plate 56. Plate 54 is free to lift, permitting free discharge from the port. Communication into the port restricts itself by seating the check plate over the port.

Accumulator piston 52 is a ring shaped member in sealed reciprocating contact with the outside wall of accumulator cylinder 58 and the inside wall of cylinder 59. A step in the wall of cylinder 58 limits the upward travel of accumulator piston 52 while the piston can move down until it contacts check plate 53. The maximum displacement (area multiplied by stroke) of accumulator piston 52 equals the maximum displacement of secondary piston 50.

Check plate 53 is part of the fluid control arrangement and is cut in the shape of a ring. It seats on closure plate 56 just below accumulator piston 52. Check plate 53 covers ports drilled in a circle in plate 56, permitting free flow out of these ports and restricted flow into these ports.

Piston region G is confined within chamber cylinder 57 and surrounds secondary piston 50 within cylinder 57. Piston region G communicates through ports in the wall of cylinder 57 with the annular space between chamber cylinder 57 and accumulator cylinder 58. From this space, piston region G communicates through inter-drilled holes in plate 56 with the port openings under control check plate 53. Piston region G also communicates through external piping to check valve V22. Piston region G is filled with hydraulic fluid.

The bore of chamber cylinder 57 is relieved on its upper portion to a diameter greater than diameter U of the secondary piston flange. This permits unrestricted flow of piston region hydraulic fluid above and below the secondary piston flange. Just below the wall ports, the bore of cylinder 57 decreases in diameter to a fitted female engagement with the male secondary piston flange, forming secondary stopping cushion means GG at the lower end of the secondary piston travel.

Accumulator region H is confined between accumulator cylinders 58 and 59 below accumulator piston 52 and above control check plate 53. Region H also communicates through a drilled hole in check plate 53 and a passage in closure plate 56 with external bi-pass control valve V17. Accumulator region H is filled with hydraulic fluid.

Region J is confined in external piping and a drilled passage in plate 56 between valves V17, V20, and V22 and the port opening under check plate 54. Region J is filled with hydraulic fluid. Region L is confined in the external hydraulic circuit between valves V23, V24, V20, and V21.

Valves V24 and V23 fill and bleed regions G, H, J, and L from the main hydraulic circuit. Once set, the total volume of fluid of the four regions does not change during operation of the machine.

Region K is confined between inner and outer accumulator cylinders 58 and 59 below upper plate 55 and above accumulator piston 52. Valves V25 and V26 fill and bleed region K with accumulator pressure gas,

pressurizing the accumulator fluid control system. Once set, the quantity of accumulator pressure gas in region K remains constant during machine operation.

Second tooling member 2 resets on and is supported by the upper end of secondary piston 50. First tooling member 1, the primary piston chamber, the second tooling member 2, and the secondary piston chamber assembly are all disposed centered along a common axis.

The underface of the first tooling member is fitted with tapped holes, T-slots or other means for attachment of the upper halves of forming dies. The upper face of the second tooling member is fitted in similar manner with means for attaching the lower halves of forging tooling. Hydraulic piston 93 located in a bored hole in the upper face of second tooling member 2 provides means for ejecting formed parts from the lower tooling. Similar means can be provided in the first tooling member for stripping parts from the upper tooling.

FIG. 7 shows the forming cycle of the first embodiment machine in five steps. Step I shows the machine in the stroke position. Steps II, III, and IV show the rapid succession of forming, stopping of the first tooling member, and stopping of the second tooling member. Step V shows the machine reloaded and the primary pressure gas reset preparatory for another stroke.

STEP I — Ready to Stroke

First tooling member 1 is held at stroke position in the following way: gas region B is temporarily confined between the engaged faces of primary piston head 4 and face flange 23 attached to the lower end of opposed reset piston 5. Reset seal 10 carried on the outside diameter of face flange 23 isolates region B from primary pressure gas of region A. Region B, connected to external control means through sleeve 24 and passages in the first tooling member, is at this step depressurized and vented to atmosphere by the external control. The pressure of region A acts down on face flange 23 clamping opposed piston 5 to the primary piston head.

Primary pressure in Region A is transmitted by collar piston 6 to fluid in intermediate region C. Since diameter P is greater than diameter N, the area of primary region A pressure acting down on top of the primary piston head is less than the under head area acted upon by equal pressure in intermediate region C. Thus a net upward thrust is acting on the clamped together primary and opposed pistons, and they press up against the hydraulic fluid which at this step is trapped in hydraulic actuation chamber E.

The second tooling member is held at forming position in the following way: The weight of the second tooling member presses down through secondary piston 50 on the hydraulic fluid in piston region G, creating a certain pressure. This pressure communicates through the inter-drilling past control check plate 53 to accumulator region H below accumulator piston 52. Accumulator pressure gas in region K above piston 52 is set at a slightly higher pressure than the weight induced pressure in piston region G. At this step the dead weight of the second tooling member is not sufficient to displace fluid from piston region G and lift accumulator piston 52 against pressure gas in region K.

STEP II — Stroke Initiation and Forming

The primary pressure gas is released to urge the first

tooling member in a downward stroke in the following way: Stroke initiation valve V11 closes temporary region B off from atmosphere and connects region B to the primary pressure gas of region A. Primary pressure gas enters region B and now acts down on the entire face area of primary piston head 4. The first tooling member moves down, separating away from opposed piston 5. Once radial seal ring 10 has cleared engagement wall 47 on the upper face of piston head 4, primary pressure gas flows directly over the top of piston head 4 thrusting the first tooling member downward. In so doing, the primary pressure gas expands, releasing its energy to the first tooling member.

Region C intermediate fluid moves down preceding piston head 4 and causing collar piston 6 to displace downward at a proportionally slower speed than that of the first tooling member.

Forming occurs in the following way: At some point in stroke the upper tooling contacts the work piece resting in the lower die. The work piece deforms and the resulting forging force acts upwards decelerating first tooling member 1 and acts downward, accelerating second tooling member 2. When the first tooling member has decelerated and the second tooling member has accelerated to an equal velocity, metal deformation ceases.

While metal deformation is occurring, the inertial forging force acting downward on the second tooling member far exceeds the upward acting force exerted by secondary piston 50, because the piston force depends on fluid pressure sustained in piston region G by the annular control accumulator and by the accumulator pressure gas of region K. The secondary piston yields to the overbalance of forces during forming and permits the second tooling member to accelerate and move downward. Simultaneously, hydraulic fluid is displaced from piston region G into accumulator region H and accumulator piston 52 yields and moves in an upward direction.

STEP III — Stopping of First Tooling Member and Tooling Separation

After forming, the first tooling member may have residual downward velocity. It may be traveling at the same velocity as the second tooling member with the upper and lower tooling stuck together. Or if the forging is shallow and the forming tonnage high, elastic energy stored in the tooling during impact springs the tooling members apart after forming, further slowing the first tooling member while giving an additional velocity boost to the second tooling member.

Primary stopping of the first tooling member occurs after forming in the following way: At some limiting point in mid-stroke, primary piston head 4 engages collar piston 6. If the first tooling member travels below this point, it pushes collar piston 6 with it, expanding the volume of intermediate region C. When this happens, the low gas pressure of region F moves fluid replenishment piston 7 downward, pushing fluid from region D past check plate 8 to replenish fluid in intermediate region C as the collar piston recedes downward. Primary pressure of region A, acting upward on the collar piston against the low replenishment pressure acting down in region C, creates a net upward thrust which decelerates the collar piston and the first tooling member with it.

Thus though the first tooling member impacts and is slowed by the second tooling member, primary stopping of the first tooling member results from the collar piston arrangement acting independently of the second tooling member. As the second tooling member moves away, primary stopping of the first tooling member is sustained independently by reaction to the machine frame. By independently limiting and halting the first tooling member while permitting the second to continue in motion, the tooling is caused to separate and pull apart directly following a forming blow.

As will be discussed shortly, the height of the second tooling member forming position is adjustable. It should ideally be set so that forming ceases just as the primary piston head engages the collar piston; e.g. at the end of the first tooling member acceleration stroke. Self-destructive effects to the primary piston head and collar piston when they engage at this point are eliminated by the hydraulic cushion recess CC in the upper face of the collar piston.

As the first tooling member is stopped and the second tooling member continues downward, fluid is displaced from piston region G into accumulator region H.

STEP IV — Stopping of the Second Tooling Member

After the first tooling member and collar piston 6 have been brought to zero downward velocity, they return upward to an equilibrium rest position in the following way: when the downward motion has been halted, primary pressure gas of region A acts upward on the collar piston, pressurizing expanded intermediate region C. Intermediate region C fluid meters back through restricted ports or holes in check plate 8 into lower pressure region D, thereby raising replenishment piston 5. Collar piston 6, and the first tooling member engaged with it, move upward at a controlled velocity until intermediate region C is reduced to its original volume. Replenishment piston 7 contacts its up stop and motion is halted. At this point the first tooling member is in its limiting rest or equilibrium position; the distance of this position in direction toward the second tooling member is determined and limited by the collar piston arrangement. Correspondingly, at this rest position, the region A primary gas has its most expanded volume and is in the condition of lowest stored energy permitted by the collar piston stopping arrangement.

Secondary stopping of the second tooling member occurs in the following way: Initially and during most of its downward travel, second tooling member motion is yieldably resisted by the piston region back pressure attendant to lifting accumulator piston 52 and compressing accumulator pressure gas in region K. If the second tooling member still has downward velocity as it nears the bottom of its travel, secondary piston 50 enters the secondary stopping cushion GG formed at the lower end of chamber cylinder 57. Piston region G fluid displacing from within the stopping cushion must pass through the orifice clearance between the secondary piston flange 51 and the inner wall of chamber cylinder 57. The resulting intensified hydraulic pressure acts upon the secondary piston, bringing the second tooling member to a rapid stop. The cushion depth, radial clearance and the area of secondary piston flange 51 are designed to absorb the maximum possible second

tooling member kinetic energy without impact or damage to the machine or foundation.

Once the second tooling member downward motion has been halted, the second tooling member does not automatically return upward to forming position. Instead it is maintained in the down position until the machine operator signals it to be raised to forming position. The placing of check plate 53 between piston region G and accumulator region H prevents the accumulator pressure of region K from acting directly back into piston region G and from automatically lifting secondary piston 50 and the second tooling member back to forming position. Thus, once the tooling has separated and opened after a single forming blow, it cannot reclose, retouch or restrike until after the operator reloads the die and signals the secondary fluid controls to raise the second tooling member.

STEP V — Reset System Compresses Primary Pressure Gas

Within milli--seconds after stroking, the machine has gone through Steps II, III and IV; the first tooling member has moved to rest position; the second tooling member has moved to bottom position. The tooling has opened. Piston 93 can immediately eject the formed part from the die, and the operator can immediately move into the machine to unload the part, reload and relocate fresh work pieces. The operator is perfectly safe since it is impossible to stroke the first tooling member from its limiting rest position.

The primary pressure gas is recompressed in the following way: Immediately after a forming stroke pump control valve V1 closes, and the hydraulic power system starts pumping fluid into hydraulic actuation region E above the opposed reset piston 5. The opposed piston is displaced downward, recompressing the gas of primary pressure region A until opposed reset piston 5 engages primary piston head 4 at limiting rest position engaging reset seal ring 10. At this point, valve V1 opens to unload the pump P1 and the opposed piston remains held down against piston head 4 by the fluid now trapped in hydraulic chamber E by external check valve V5, and the recompressed primary gas of region A is now recharged with stored energy.

RETURN TO STEP I

Once a fresh work piece has been positioned in the tooling, the operator signals the machine to move to the ready to stroke position.

The reset system causes the first tooling member to move to stroke position in the following way: Temporary region B has been recreated by the engagement of reset piston 5 down against primary piston head 4. Valve V11 depressurizes region B to atmosphere, and reset seal ring 10 cooperates to isolate the depressurized region B from primary pressure gas thereby causing the first tooling member and opposed reset piston 5 to be clamped together again by region A pressure. Check valve V5 operated by pilot valve V6 now opens, connecting region E to the low pressure reservoir in the external hydraulic system. Primary region A pressure acts upward through intermediate region C fluid to the underhead surface of the primary piston head 4. Acting on the net area between diameters O and P, this pressure lifts the first tooling member and opposed reset piston upward, displacing fluid from hydraulic actuation chamber E back to the reservoir at a velocity con-

trolled by flow valve V8. This reset motion can be halted at any stroke position by closing reservoir check valve V5, thereby locking the remaining fluid in actuation region E. And since the first tooling member can be halted of upward motion and stroked from any position above limiting rest position, the amount of primary gas expansion and thus the forming blow energy can be varied in this manner from stroke to stroke by the machine operator.

The second tooling member moves to its forming position in the following way: Operator's signal opens fluid bi-pass valve V17 connecting accumulator region H with region J and piston region G below secondary piston 50 at rest in hydraulic cushion GG. This permits region K accumulator pressure to act upwards on the secondary piston. This pressure is just sufficient to overbalance the weight of the second tooling member. Accumulator piston 52 moves downward, displacing the second tooling member, and secondary piston upwards at a velocity controlled by flow control valve V18. When accumulator piston 52 bottoms in its stroke, the second tooling member is yieldably suspended in its stroke, the second tooling member is yieldably suspended in its forming position. Valve V17 now closes and the machine can be immediately initiated to a stroke.

The operator can work in the tooling area from the moment the machine forms a part until the reset system begins to move the first tooling member to stroke position and the second tooling member is signalled to move to forming position. The only pause in the cycle when the operator cannot lubricate the dies and arrange the work pieces is during these upward motions. And since the first and second tooling members are driven upwards by gas springs (primary region A and accumulator region K), their removal to stroking position can occur very quickly in a second or less. Thus there are no awkward delays in which the operator's work waits for the machine, and the machine cycle is very efficient as a result.

The machine reset arrangement depends on the successful isolation of primary pressure in region A from temporary region B during depressurization of region B. Radial reset seal 10 therefore performs a critical function while at the same time operating under a severe condition not endured by the other seals. When valve V11 opens to initiate a stroke, very low pressure introduced into temporary region B causes the primary piston to immediately begin to move downward expanding region B as fast as the low pressure is supplied into it through sleeve 24. Thus at the instant reset seal 10 clears engagement wall 47 at the upper portion of head 4, a pressure much below that of primary pressure region A exists between face flange 23 and piston head 4. Thus as seal 10 clears, primary pressure gas of region A is suddenly released to rush into the low pressure space between the piston faces. The rush of gas past seal 10 causes the pressure on the outside of the seal to drop well below the pressure of gas held statically behind the seal inside groove 48. Thus when a stroke is initiated, the seal can fail by being blown out of its groove.

FIG. 4 shows several methods of combating this type of seal failure. The seal groove 48 can be contoured to be wider than the sectional thickness of the seal and thereby facilitate escape of static gas around the seal and out of the groove when a stroke initiating rush of

gas occurs. The pressures inside and outside the seal can be equalized in this manner. Tapering the sides to give groove 48 greater width at its entrance also assures that the farther seal 10 lifts outward during stroke initiation, the more will be the clearance through which the gas can equalize.

Equalizing passages 49 provide another method to prevent reset seal 10 from blowing out of its groove during stroke initiation. Passages 49 insure that the low pressure present in region B during stroke initiation also exists inside groove 48 behind seal 10. While the rush of pressure gas at the instant seal 10 clears engagement wall 47 produces a depressed pressure outside the seal, this depressed pressure does not fall significantly below the low pressure level of region B which is transmitted by passage 49 to the back of seal 10. Thus not being subjected to a violent pressure differential, reset seal 10 remains in its groove during repeated stroke initiations. Equalizing passages having a similar function have been used in the prior art in conjunction with seal rings retained on flat wall or face surfaces.

Besides a radial seal as shown direct face seal means such as that used in U.S. Pat. 3,093,117 of B. I. Brown can also be used to isolate region B between pistons 4 and 5 from primary pressure region A. A face seal is less effective, however, than a radial seal if the piston members engage slightly tilted with respect to each other.

The motions of the first and second tooling members during a stroke vary according to the type of forming work being performed. On one end of the forming work spectrum is hard coining blows involving flat, large area work pieces which induce very high forming loads of short duration. On the other end of the spectrum are soft blows into deep work pieces which induce low forming loads of long duration. FIGS. 8 and 9 illustrate the machine stroking motions at both extremes of the work spectrum and demonstrate that in no case do the tooling members strike more than one single blow per machine stroke. The motion curves in FIGS. 8 and 9 were mathematically derived by double intergrating with respect to time the accelerations of the machine members stroking under these two extremes in forming conditions. The computations were made for a large scale machine capable of doing 1.5 million foot pounds of forming work per stroke.

In FIG. 8, curves ST1, ST2, and ST6 represent the stroking motions respectively of the first tooling member, the second tooling member, and the collar piston. The curves are plotted against a time line which counts from the moment the stroke is initiated. As shown by curve ST1, the first tooling member under the thrust of the primary chamber moves downward, gaining velocity as it moves. Simultaneously the collar piston, as shown by curve ST6, is moving downward at a proportional, though slower, rate. After 18 inches of free stroke and just before the primary piston head catches up to the collar piston cushion, the first tooling member strikes a die to die blow against the second tooling member at approximately 0.05 seconds. During the brief instant of contact most of the velocity and kinetic energy of the first tooling member is transferred to the second tooling member which instantly attains downward velocity in accordance with the laws of perfectly elastic impact. A small percent of the kinetic energy remains with the first tooling member as it rebounds upward after impact. The thrust of the primary pressure

gas absorbs this rebound motion after 2 inches and returns the first tooling member downward again, though much too late to restrike against the second tooling member which has long since sped downward. The first tooling member enters the collar piston cushion and is independently limited from any further motion downward.

This blow generates very high coining or embossing loads which are sustained inertially by the second tooling member. The resultant foundation loading is of a much smaller magnitude and occurs only subsequent to the blow when at approximately 0.14 seconds the second tooling member has already moved downward three feet and the secondary piston 50 has entered secondary stopping cushion GG. The cushion walls are contoured to hold constant hydraulic pressure on the diameter piston area, slowing the second tooling member down and absorbing its kinetic energy. In this way, the stopping cushion force is distributed evenly during the last foot of second tooling member stroke, minimizing the secondary stopping load on the foundation.

In order to simulate the softest possible forming blow, a deep piercing operation is illustrated in FIG. 9. In this instance the first tooling member has a free stroke for only 6 inches during which to gather kinetic energy. At approximately 0.03 seconds, the piercing punch attached to the first tooling member enters the work piece waiting in the lower die. This produces a 750 ton forming force which resists further kinetic energy gains by the downward moving first tooling member while causing the second tooling member to begin moving downward and gain kinetic energy.

At approximately 0.065 seconds when the punch has pierced into the work piece 12 inches, the primary piston head enters the cushion CC in collar piston 6. The thrust of the primary pressure gas on the first tooling member reverses sharply as shown by thrust curve f_1 , in FIG. 10. The pressure gas, from acting downward over the area of the primary shaft diameter N now suddenly switches to acting upwards on the net areas of the collar piston minus the area of the primary piston head diameter R. As illustrated by curve ST in FIG. 9, this thrust reversal brings the first tooling member to a sharp halt and stops further punch penetration into the work piece.

This primary stopping means acts solely on the first tooling member and in no way reacts against or depends upon the second tooling member. As the first tooling member suddenly stops, no major stopping forces are on the second tooling member and the kinetic energy it received during penetration of the work piece carries the second tooling member along, moving it away from the suddenly halted first tooling member. In this way the tooling begins to separate immediately at the end of the penetration blow. During the blow, the punch has backward extruded a work piece shell 24 inches deep. To have a complete tooling separation, the work piece must be pulled along for at least 24 inches by the lower tooling to strip it free from the punch. A minimal stripping force of approximately 40 tons resists and absorbs second tooling member kinetic energy during these first 24 inches of separating motion. The first embodiment secondary chamber assembly, set to barely balance the second tooling member weight, offers minimal additional resistance to downward motion of the second tooling member. The pressure of piston region G acting on the diameter T area

of secondary 50 increases only slightly as the second tooling member moves downward. The pressure increase results from the upward movement of accumulator piston 52 which compresses accumulator gas region

5 K. It is minimized by allotting region K a large volume. Back pressure due to hydraulic displacement from piston region G into accumulator region H is minimized by providing large area interdrilled passageways. Though the kinetic energy imparted to the second tooling member by this extremely soft penetration blow is minimal and the second tooling member moves away from the blow at a very slow velocity, this minimal kinetic energy is sufficiently sustained by the machine and utilized to successfully strip the work piece one foot clear of the punch for three foot total tooling separation.

FIGS. 8 and 9 show that in both extremes of forming conditions the first and second tooling members separate immediately following the forming blow and never 10 reapproach one another for a restrike or for multiple 15 pounding. Full energy forming strokes which fall anywhere between these two extreme cases produce forming tonnages higher than the 750 tons induced by the FIG. 9 stroke but somewhat less than the extreme coining load induced by the FIG. 8 blow. Any such stroke 20 in the range between the two extremes will be followed by immediate tooling separation due in modified degree to elastic bouncing apart as in FIG. 8 and to independent stopping of the first tooling member while 25 kinetic energy induced by the forming carries the second tooling member away as in FIG. 9. Having separated in this way, following any intensity forming blow, the tooling members never restrike each other; the first tooling member can never move beyond its limiting rest position 30 toward the second tooling member; and the second tooling member, after having moved beyond the first tooling member's rest position, does not return back 35 toward the first tooling member and forming position except in response to the operator's signal after he has 40 released the die. This absence of restrike reduces impact fatiguing of dies to the minimal levels required in the forging industry. With reduced shock harder tool steels can be used, resulting in greater resistance to die 45 wear and washout. The use of high hardness dies for cold forming work is also made practical.

The machine foundation, as has been noted, must be 50 designed to sustain the downward acting thrust resulting when the second tooling member engages secondary stopping cushion GG after a high tonnage blow. Because the machine frame is rigidly anchored to the 55 foundation in this first embodiment of the invention, the foundation must also sustain the accelerating and stopping thrusts which actuate the first tooling member during a stroke. Referring to thrust curve f_1 , in FIG. 10, during its travel from stroking position to limiting rest position, primary pressure gas exerts a thrust urging the first tooling member downward. Simultaneously this thrust acts upward with equal force on the primary chamber assembly and along with it, the machine frame and foundation. Since the weight of these stationary machine parts is not as great as the upward thrust, the foundation must be weighted or ballasted to keep the machine from rising or jumping when a stroke is initiated. Also when the first tooling member is stopped by the collar piston cushion at limiting rest position, the thrust on the stationary portion of the machine reverses 60 and acts downwards. The foundation must be able to 65

sustain this stopping load. As can be seen from curve f_1 , the acceleration and stopping thrusts are almost constant; the large volume of primary pressure gas in region A varies very little during a stroke and as a result, its pressure, which produces these thrusts is subject to only minor adiabatic variation. It is because these thrusts are moderate and fully determinable that a foundation can be built rigidly attached with the machine frame.

In the example in FIG. 9, the punch moves into the work piece, forms a 24 inch deep shell, and strips clear of the part, all in 0.250 seconds. In smaller scale machines, forming smaller parts, this time element is less. Thus in hot forming work, the upper tooling is in contact with the hot work-piece for milliseconds, while ejection of the part from the lower tooling begins milliseconds after forming. Tooling exposure to heat is reduced to the barest time necessary to forming, and heat check resistance is no longer a great limitation in the selection of die materials. Harder, more washout resistant hot work tool steels can be used.

Besides its function of stopping the first tooling member for quick tooling separation, the collar piston must, for safety sake, be able to completely stop the first tooling member if the machine is accidentally stroked while the second tooling member is in its down position or during changeover when no dies are in the machine; e.g., if the first tooling member strokes without being able to reach the second tooling member for impact. If the collar piston does not stop the first tooling member in this case, shaft closure plate 11 will be struck causing destruction to the machine and the foundation. For this reason the collar piston must be capable of arresting by itself the kinetic energy of a full first tooling member stroke. If the primary stopping thrust on the first tooling member equals twice the first tooling member acceleration thrust, then the collar piston stopping stroke below limiting rest position must at least equal half the full first tooling member stroke above limiting rest position.

The volume of fluid in intermediate region C is very critical since it determines the limiting rest position and the portions of the total mechanical stroke given over to accelerating and stopping the first tooling member. If the volume of fluid in region C is small, the collar piston assumes a higher position in the primary chamber, and the collar piston is engaged sooner at limiting rest position as the first tooling member strokes. The first tooling member acceleration stroke is short and the primary stopping stroke long. Conversely, if the volume of intermediate region C is large, the limiting rest position is lower, the acceleration stroke is long, and the stopping stroke is short. The volume of intermediate region C must be set small enough and the stopping stroke set long enough, for the collar piston to completely stop the first tooling member during a mis-stroke without impacting closure plate 11. The operator can visually monitor the volume of intermediate region C by observing the limiting rest height of the first tooling member after each blow.

Also, the total displacement of replenishment piston 7 must be great enough to keep intermediate region C replenished with hydraulic fluid throughout a maximum first tooling member stopping stroke. If the region D volume cannot completely replenish region C, then at the end of a maximum stopping stroke, the collar piston will be confronted with a vacuum in region C in-

stead of full intermediate fluid trapped by check plate 8. Such a lack of fluid in intermediate region C will permit the stopping thrust to continue acting after the first tooling member is stopped, accelerating the collar piston and first tooling member back upwards until the deficient fluid volume in region C is impacted, causing shock pressurization and possible breakage of the large and small inner cylinders 14 and 15.

Primary stopping of the first tooling member operating independently of second tooling member position permits a wider application of the high velocity impact forming method. Some previous machines in this art rely entirely on the presence of a work piece to halt the stroke of the tool carrying members. Operations in which the tooling cuts or punches through the work piece cannot be performed because the tool carrying members will continue to stroke unimpeded as the part is punched through and undesirable collision of the dies will occur. However, when operations of this kind are performed using the present invention, the collar piston stops the upper member immediately after the work is completed, preventing the upper tooling from over-stroking into the lower tooling. Such operations as shearing, flash trimming, piercing, and stamping are readily performed on this machine.

FIG. 2 illustrates a method of supporting the second tooling member on the upper end of secondary piston 50 which permits easy mechanical adjustment of the second tooling member height without impairing the secondary piston stroke. Elevating block 90 is in screwed engagement with the inner wall of screw sleeve 88. The weight supporting force of secondary piston 50 is transmitted to elevating block 90 resting on the piston's upper end, and in turn to screw sleeve 88 and the second tooling member resting on the upper end of the screw sleeve. The outside wall of screw sleeve 88 is in geared engagement with pinion 89. The pinion shaft located in a vertical hole through the second tooling member is mechanically locked to pinion nut 92. As pinion nut 92 is rotated by a wrench or other means, pinion 89 rotates sleeve 88 about the vertical axis. Elevating block 90 is prevented from rotating by anti-rotation pin 91 and screws vertically as sleeve 88 rotates, raising or lowering the second tooling member in relation to the upper end of secondary piston 50. Lock plate 95 and bolt 96 lock the pinion from rotating once the desired second tooling member height is set.

For the purpose of illustrating the invention, this elevating means need not have been included, and the second tooling member could have been shown suspended directly by the upper end of piston 50. The adjustment is worthy of discussion, however, because it permits flexibility and economy in the design of the tooling. This adjustment frees dies from having to have any greater depth than dictated by the forming, and expensive stack-up plates to bridge a fixed daylight are made unnecessary. With the daylight adjustable, the designer can proportion the tooling weights in favor of the type of forming work to be performed. In high tonnage shallow work where a higher percentage of the energy output being distributed into deformation work is desired, more weight can be given to the lower tooling to increase the second to first tooling member mass ratio. In deep low tonnage work, where higher second tooling member residual kinetic energy and a greater tool opening distance after impact are desired, more weight and mass can be apportioned to the upper tooling, de-

creasing the second to first tooling member mass ratio.

As noted earlier, the energy of each blow can be controlled from zero to full intensity by varying the height to which the first tooling member is removed just before stroking. This permits the machine to do forming work in a series of blows with the energy of each blow individually gauged to the amount of deformation to be accomplished by that blow. During some multiple blow operations it may be desirable for the second tooling member forming position to vary along with the stroke energy of the first tooling member. For instance, a work piece might be flanged out or headed on the first blow and deep pierced on the second. For the first blow, the second tooling member must move the work piece up just near enough to where it can be hit just ahead of the first tooling member's engagement into the collar piston. For the second blow the second tooling member must move the work piece much higher in order that piercing begin just after the first tooling member is stroked and in order that most of the first tooling member stroke be devoted to deforming the work piece.

The second tooling member forming position is readily varied from stroke to stroke in the following way: Referring to FIG. 2, accumulator hydraulic region H below accumulator piston 52 in the secondary chamber assembly is connected through external circuitry with region L in the piston end of hydraulic cylinder 77 mounted near the tooling region of the machine. Region M in the rod end of cylinder 77 is connected into the external hydraulic system through directional control valve V19. Piston 76 and piston rod 75 reciprocate vertically as shown in cylinder 77. The face area of piston 76 equals the sectional area of secondary piston 50 at diameter T. Pointer 74 is attached to and can be adjustably located along piston rod 75 by screwing or other means to correspond to the height of a selected feature on the lower tooling when the second tooling member is in its forming position.

Between forming blows, while the second tooling member is down, hydraulic fluid can be transferred between accumulator region H and region L. If valve V19 is shifted to exhaust region M, and if bypass valve V17 opens, the fluid from region H will flow past check valve V20 into region L, and the accumulator piston along with pointer piston 76 will displace downwards. If valves V1, V17, and V4 are closed and if valve V19 is shifted for pumping fluid into region M, and fluid in the region L end of cylinder 77 will flow past check valve V21 into accumulator region H. The accumulator piston 52 and pointer piston 76 will displace upwards. Fluid displaced into region L detracts from the fluid volume in accumulator region H which must displace the second tooling member up to its forming position. Since the pointer piston has the same face area as secondary piston 50, the distance pointer 74 is moved downward by fluid transfer equal the distance the second tooling member, when raised, falls short of its uppermost forming position. Thus before each blow the operator can select the height to which he wants the second tooling member to raise simply by positioning pointer 74 with control valves V19 and V17.

After low energy blows and deep forming blows, the second tooling member may lack the kinetic energy to cause the secondary chamber to yield sufficiently and the second tooling member may not separate downward far enough from the upper tooling for the opera-

tor to unload and relocate the work piece in the dies. In such cases, the operator can lower the second tooling member further by shifting valve V19 to exhaust region M; the weight of the second tooling member will displace fluid from piston region G past check valves V22 and V20 through region J into region L. As the second tooling member moves downward, pointer 74 moves downward at the same rate, showing how much the second tooling member forming position is also lowered. If the operator wishes to raise the second tooling member to the same forming position as before the blow, he can, by control valve means already described, transfer the fluid just received by the region L end of cylinder 77 into accumulator region H below accumulator piston 52, adding back to the fluid volume which raises the second tooling member to its forming position. In so doing, pointer 74 returns to its original height as does the second tooling member when bypass valve V17 is again opened.

Since this invention relies heavily on hydraulic fluid and energy absorption by hydraulic cushions, means for maintaining constant hydraulic fluid temperature is required for consistent performance. Cooling element H1 absorbs the heat from fluid discharged from hydraulic region E. Element H2 together with circulating pump P2 maintains an even temperature in intermediate region C. Element H3 provides cooling means for regions G, H, and J in the secondary chamber.

In FIGS. 1 and 2, the first and second tooling members are guided in line with each other by the common frame assembly. Spacer members 82 pre-stressed in compression and horizontal tie rods 81, pre-stressed in tension, clamp side frames 80 a set distance away from each other at the mid-section of the machine. Shaft closure plate 11, together with dowels 94, holds side frames 80 a set distance apart at the upper portion of the machine. Guide ways 86 are attached to the upper end of the side frames and provide appropriate surfaces for the first tooling member to reciprocate against. Guide ways 85 are attached to the lower portion of frames 80 and provide appropriate surfaces for the second tooling member to reciprocate against.

If off center forming work is performed in the machine, the first and second tooling members are induced to rotate during impact. This rotation acts to spread side frames 80 away from each other. Bending reactions in the side frames and tension forces set up in tie rods 81 and closure plate 11 act to constrain this rotation and maintain the tooling members in axial alignment. Since the side frame assembly is not subjected to direct inertial forming loads, it can be built as ruggedly as is desired to constrain maximum eccentric loading.

Second Embodiment

In the second embodiment machine depicted in FIGS. 11 and 12, side frames 280 are not anchored rigidly to a fixed foundation. They are instead supported by flexible gas cushions 2L confined in vertical bored holes above pistons 288. Cushions 2L communicate through drilled passages with external fill and bleed controls, and once filled, the quantity of gas in these cushions need not be altered during the operation of the machine.

When the machine is not in motion, cushions 2L are compressed to a pressure which sustains the weight of the side frames and upper portion of the machine; this

weight is transmitted through the cushions to the foundation. When the machine strokes and first tooling member 201 is accelerated downward, the accelerating thrust acts simultaneously upwards to raise the common frame assembly. The frame up motion causes cushions 2L to expand and drop in pressure, decreasing the downward force on the foundation. But no up lifting thrust due to first tooling member acceleration is transmitted to the foundation, and thus no foundation ballasting is required with this second embodiment of the invention as is the case for the anchored frame in the first embodiment.

Primary stopping of the first tooling member occurs only after the first tooling member has been accelerated downward and the side frame assembly has simultaneously been accelerated upwards. That is, stopping the first tooling member stroke with respect to the machine frame occurs only when cushions 2L are expanded. Therefore, downward reaction to primary stopping is never transmitted to the foundation in this arrangement.

While the center of gravity of the first tooling member and common frame assembly remains at a relatively constant height when this second embodiment machine strokes, the two members gain potential energy with respect to gravity because the side frames rise above the height where their weight is fully supported by cushions 2L. As stroking ceases, the two members fall under the influence of gravity and the gained potential energy is transformed into downward kinetic energy which in turn causes an overcompression of support cushions 2L after a stroke. The amount of overcompression depends on the quantity of gas in regions 2L and how high the side frames are driven during a stroke. Typically this cushion pressure build-up after each stroke may exert a downward force on the foundation as great as twice the weight of the machine. Such a load is negligible, however, and the principal source of downward thrust on the foundation of this second embodiment machine is the reaction to stopping the second tooling member which is transmitted by the secondary piston chamber resting directly on the foundation.

The primary chamber depicted in FIG. 11 operates in essentially the same manner as the first embodiment primary chamber. Instead, however, of primary stopping by means of a collar piston, the second embodiment incorporates a means of primary stopping used previously in such pneumatic actuator patents as B. I. Brown U.S. Pat. No. 3,093,117 and J. B. Ottestadt U.S. Pat. Nos. 2,979,938 and 2,949,096. This means consists of confining a separate cushion region 2C surrounding primary shaft 203 within inner cylinder 215 and below primary piston head 204. Isolated from communication with primary gas pressure in region 2A by seal means 228 and from the chamber exterior by shaft closure plate 211 and seal means 227, this shaft end cushion region is charged with a fixed quantity of pressure gas which need not vary during operation of the machine.

Though its function remains unchanged, opposed reset piston 205 in this second embodiment has slightly altered construction. As shown in FIG. 11, the opposed piston reciprocates in a deep bore in head closure plate 212. Hydraulic actuation region 2E is confined in that bore above opposed piston 205 and is isolated from primary gas region 2A by seal means 233 which moves

with the opposed reset piston. The downward stroke of reset piston 205 is limited in this embodiment by a headed tailrod 222 which extends through the head closure assembly of the primary chamber. Seal means 237 confines hydraulic region 2E where the tailrod exits the chamber. The tailrod also provides drilled passage means for communicating temporary region 2B with external depressurizing and stroke initiating controls. This opposed piston arrangement is equally applicable to the first embodiment primary chamber where a collar piston is used.

Primary pressure gas region 2A in this second embodiment is confined between outer cylinder 213 and inner cylinder 215. It communicates across the upper end of inner cylinder 215 with the upper face of primary piston head 204 but cannot in this embodiment communicate with primary piston shaft 203.

As depicted in FIG. 11, the first tooling member is in stroke position. Temporary region 2B is confined between the engaged faces of the opposed piston and primary piston head. Region 2B is depressurized to atmosphere and isolated from primary gas region 2A by reset seal 210 bonded on the primary piston head face. Seal 210 in this embodiment is disposed in female relation to the flange of reset piston 205. Cushion pressure in 2C acts over the area between diameters 2R and 2N and exerts an upward force on the underhead surface of the primary piston head. This force is greater than the primary pressure of region 2A acting downward on the primary piston head over the area between diameters 2R and 2P. Thus a net upward force is pressing the primary piston head against the opposed reset piston and in turn against hydraulic actuation fluid locked in region 2E.

A stroke initiation control repressurizes region 2B using an external pressure source and the force balance is upset. Pressure, acting now on the entire primary piston head area, creates a greater force than that acting upwards due to stopping cushion pressure in shaft end region 2C. The first tooling member moves downward. Once seal 210 clears the face flange of opposed piston 205, the first tooling member is acted upon by the net thrust of the primary pressure gas 2A acting down on the piston head area of diameter 2R minus stopping cushion pressure of region 2C acting up on the underhead area between diameters 2R and 2N. The gas pressures of primary region 2A and cushion region 2C are set so that initially the net thrust acts downwards accelerating the first tooling member toward the second tooling member.

As the first tooling member strokes, the primary gas expands in volume and the stopping cushion in the shaft end region compresses. The primary pressure drops adiabatically and the stopping cushion pressure of region 2C increases adiabatically. At some limiting stroke position both terms become equal and the thrust F201 on the first tooling member is zero. If the machine is stroking with the second tooling member accidentally beyond stroking reach of the first tooling member, the first tooling member continues downward beyond this limiting equilibrium position, compressing stopping cushion 2C to greater pressures. The thrust becomes increasingly negative, decelerating the first tooling member until its downward motion is completely stopped.

The solid line curve F201 in FIG. 10 is a sample plotting of the above thrust expression during an entire free stroke of the first tooling member. The calculation is

based on a second embodiment of the primary piston chamber having the same energy output and the same total mechanical stroke as the first embodiment primary chamber whose thrust characteristic F1 is shown dotted. The comparison in FIG. 10 illustrates the superiority of primary stopping through use of a collar piston because it minimizes and controls thrust peaks and thus permits the machine frame to be mounted rigidly to its foundation. On the other hand, while the second embodiment stopping cushion results in much higher thrusts for a given energy output, these thrust peaks are not detrimental if the common frame assembly is mounted on gas support cushions 21 as illustrated in FIG. 12. As already discussed, reaction for first tooling member acceleration and stopping in the second embodiment is taken inertially by counter motions of the frame assembly and the high primary chamber thrusts F201 are not transmitted to the foundation at all.

The first tooling member is reset to stroke position in the same manner used in the first embodiment. After a stroke the first tooling member motion ceases at limiting rest or balance position where the primary chamber thrust F201 is zero. Hydraulic power means delivers fluid into actuation chamber 2E forcing opposed piston 205 downward. During this motion the primary gas in region 2A compresses and slowly increases in pressure and stored energy. Maintaining the thrust balance, stopping cushion 2C compresses proportionately and the primary piston head, at limiting rest, moves downward though at a much slower rate than opposed piston 205. After reset seal 210 is engaged by the opposed reset piston, temporary region 2B is depressurized to atmosphere. When region 2E fluid is released to an atmosphere reservoir in the external hydraulic system, the force acting on the engaged first tooling member and opposed piston assembly is the net thrust of primary pressure gas acting downward on the area between diameters 2R and 2P against stopping cushion pressure gas acting upwards on the area between diameters 2R and 2N. This force removes the two members to the stroke height desired at which point the operator shifts a control valve halting the exhaust of hydraulic fluid from region 2E.

The secondary piston chamber assembly shown in FIG. 11 functions in the same manner as its counterpart in the first embodiment. The arrangement of accumulator piston 250 has been altered, however, by inverting its motion. It is now gas pressurized from below by accumulator gas region 2K, and hydraulic fluid enters and exhausts from accumulator region 2H through drilled passages in upper closure plate 255 above the accumulator piston. This permits more direct routing of the passages to piston region 2G inside chamber cylinder 257 and eliminates an intermediate inner cylinder 58. When the second tooling member and secondary piston 250 are propelled downward, hydraulic fluid from piston region 2G is displaced past check plate 253 into accumulator region 2H, and accumulator piston 250 is moved downward. Return motion upward is blocked by check plate 253 until bypass valve V217 is opened by operator signal, permitting the accumulator piston to displace hydraulic fluid out from its region 2H back into piston region 2G. To facilitate raising secondary piston 250 from its stopping cushion 2GG, a drilled passage and check plate 254 retained in the lower end of the secondary piston give hydraulic fluid unrestricted entry into stopping cushion 2GG while block-

ing fluid exhaust when the second tooling member is stopping. This second embodiment of the secondary piston chamber can be adapted with a forming position height selecting piston similar to that described in the first embodiment machine.

The motion of the second tooling member 202 over the range of forging conditions is the same as the second tooling member movement ST2 illustrated in FIGS. 8 and 9. First tooling member 102 also follows essentially the same stroke curves ST1 as its first embodiment counterpart in FIGS. 8 and 9. Following impact, however, the curve of first tooling member 201 may have a small magnitude oscillatory characteristic as residual velocity following a forming blow is dissipated in alternating over compression of primary gas region 2A and stopping cushion 2C. The first tooling member oscillates up and down about the limiting rest position which in turn oscillates at a slower rate as the common frame assembly falls and rises in interaction with support cushions 2L. As first tooling member 201 hones in on its limiting rest position, second tooling member 202 speeds downward; in no case does the second embodiment machine strike a second blow following impact.

Suspending the common frame assembly on gas cushion springs 2L permits an attractive alternate to the tooling daylight screw adjustment used in the first embodiment machine. In FIG. 12 hydraulic region 2M is confined by pistons 288 and 287 and by seal means 289 and 290 in the frame cushion bores. Drilled passages in support pistons 287 communicate regions 2M with external fill and bleed controls. The frame assembly and first tooling member are raised or lowered with respect to second tooling member 202 by simply adding or exhausting hydraulic fluid from regions 2M. To insure that all pistons 288 move to the same height and that all regions 2M and 2L are maintained with identical volumes, valves V219 should be closed, isolating regions 2L from each other while hydraulic fluid is present in regions 2M. This precaution is taken so that if one piston 288 has more moving friction than its companions, greater pressure will be exerted on it until it assumes the identical height. If more daylight is required for removal of a formed part than is available with the second tooling member at bottom position, then regions 2M can be filled and then bled between strokes to raise the frame and first tooling member the needed additional distance. The deep punch forming depicted in FIG. 9 is a case in which this capability is a great aid.

Side frames 280 embody a feature which greatly increases the value of this invention for automated production. If the frames are built sturdily enough to permit access holes 280A, the machine can be loaded and unloaded from the side, a practice commonly used to speed production on fly wheel presses.

Tie rods and nuts 281 and 283 together with spacers 282 are used again to lock the frames together at the mid-section of the second embodiment machine. At their upper ends, frames 280 are attached to shaft closure plate 211 with dowels 294 and bolts 284 transmit primary chamber lifting thrusts to the side frames.

Third Embodiment

FIG. 13 shows a third version of this invention with the frame assembly again rigidly anchored to the foundation. Since no frame oscillation occurs, the motions

of first tooling member 301 and second tooling member 302 exactly follow the curves, ST1 and ST2, in FIGS. 8 and 9. Reaction for acceleration and stopping the first tooling member is taken by the ballasted foundation.

The third version primary chamber combines primary stopping using a collar piston with an innovation in the method of resetting the first tooling member to stroke position. Collar piston 306, replenishment piston 307, check valve plate 308, intermediate hydraulic regions 3C and 3D, and gas region 3K are arranged and operate in exactly the same manner as their counterparts in the first embodiment. Primary pressure gas in region 3A communicates through ports at the lower end of inner cylinder 314 with the under surface of collar piston 306.

Instead of reciprocating in hydraulic chamber means in upper plate 312, inner reset piston 305 now reciprocates with inverted motion in inner cylinder 315 above primary piston head 304. Inner piston region 3E is confined inside inner cylinder 315 between reset piston 305 and primary piston head 304. Seal means 328 prevents region 3E from communicating with region 3C. Region 3E is chargeable with hydraulic actuation fluid and communicates with the external hydraulic power means, through delivery tube 322 which is rigidly attached to inner reset piston 305 and has sealed entry into a drilled passage in head closure plate 312. Primary pressure region 3A confined between inner cylinder 314 and outer cylinder 313 communicates across the upper end of cylinder 315 to inner reset piston 307. Seal means 333 prevents communication between regions 3A and 3E. In the position shown temporary region 3B is confined between inner reset piston 305 and head closure plate 312. Reset seal ring 310 similar to that used in the second embodiment is mounted on head closure plate 312, preventing primary region 3A pressure from entering temporary region 3B. Seal means 337 prevents communication between regions 3E and 3B where delivery tube 322 passes into head closure plate 312.

The third embodiment primary piston chamber is shown in the ready to stroke condition. Hydraulic actuation fluid is trapped in region 3E by external valve means. Region 3B is depressurized to atmosphere by external control means. First tooling member 301 is held up against hydraulic fluid trapped in inner piston region 3E by primary gas pressure transmitted through region C to the underface area of primary piston head 304. Hydraulic fluid in region 3E, being pressurized by the primary piston head, holds inner reset piston 305 against head closure plate 312. The first tooling member stroke is initiated by introducing pneumatic pressure into region 3B with external stroke controls. This repressurization of temporary region 3B overbalances the primary gas pressure holding the first tooling member and reset piston up. The two members move downward; once reset piston 305 clears seal 310 primary gas pressure of region 3A acts downwards on the reset piston face producing a net thrust on the first tooling member equal to the primary pressure times the area of primary shaft 303. The first tooling member and inner reset piston accelerate downward until the collar piston hydraulic cushion 3CC is engaged at limiting rest position. Motion below this point is resisted by primary region 3A pressure acting net upwards on a net thrust area equal to the collar piston area minus the primary

piston head area. Thus, the primary chamber thrust follows the dotted curve configuration F1 in FIG. 6.

First tooling member 301 is reset from its limiting rest position by first delivering hydraulic actuation fluid 5 into inner region 3E from the external hydraulic power system. This displaces inner rest piston 305 upwards until seal 310 is engaged and region 3B is reisolated. Region 3B is depressurized to atmosphere by external control, and region 3E is now opened to reservoir 10 exhaust. Primary region 3A pressure, transmitted to the underhead face of the primary piston head, lifts that member and displaces the hydraulic fluid from inner piston region 3E. The first tooling member resets upwards and is halted at any desired stroking height by 15 closing region 3E off from exhaust by external hydraulic control means.

FIG. 13 shows a third alternate method of constructing the secondary piston chamber assembly, the principal advantage of which is compactness. Upper plate 355 rests on tube spacers 371 a set distance above closure plate 356. Bolts 370 clamp the upper plate 355 and closure plate 356 in assembly. Secondary piston 350 reciprocates vertically in chamber cylinder 357 affixed through the center of plate 355. Valve piston 353 has a short vertical stroke permitting its valve face to move downward from its valve seat surface 353A in upper plate 355. Valve piston 353 is guided about diameter 3T by annular shaped accumulator piston 352; a small cylindrical extension on the bottom of valve piston 353 is in guiding engagement with a pocket in closure plate 356. Accumulator piston 352 reciprocates at diameter 3V in a recess in upper plate 355 and at diameter 3V it reciprocates against a raised hub portion of 20 closure plate 356. Piston region 3G is confined within chamber cylinder 357 above the valve face of piston 353 and below secondary piston 350. Seal means 362 prevents leakage to the chamber exterior. Accumulator hydraulic region 3H is confined between upper plate 355 and accumulator piston 352 and surrounds piston region 3G. Seal means 364 prevents region 3H from 25 communicating with the chamber exterior. Accumulator pressure gas region 3K is confined below accumulator piston 352 and valve piston 353 above closure plate 356. Seal means 365 prevents communication with the chamber exterior, and seal means 363 prevents communication between regions 3H and 3K. Once set, the 30 quantity of accumulator pressure gas in region 3K need not change during machine operation. Once set the total volume of hydraulic fluid in regions 3G and 3H should not be altered during operation of the secondary piston chamber.

The principle of operation of this secondary piston chamber is the same as the previous two embodiments. 35 As the secondary piston strokes downward after impact, hydraulic fluid is displaced past a checkvalve means into a region pressurized by an accumulator piston. The fluid remains trapped in this region due to the check valve closing action until by-pass valving directs 40 the fluid back to below the secondary piston which it then displaces upwards; in the previous two support actuators the check valve means consisted of check plates 353 and 253. In this actuator, the check valve means is 45 valve piston 353, and interdrilled passages are eliminated, allowing less constricted displacement of fluid from the piston region into the surrounding accumulator hydraulic region.

When the second tooling member is in its forming position, valve piston 353 is held against its valve seat surface 353A in plate 355 by the pressure of region 3K accumulator gas acting on the area of diameter 3T. Surrounding accumulator fluid in region 3H is in this way isolated from piston region 3G. Piston region 3G is pressurized by the weight of the second tooling member. Region 3H pressure is in ratio to region 3K pressure by the area ratio of the area between diameters 3U and 3T to the area between diameters 3V and 3T. Accumulator pressure gas in region 3K is set so that accumulator fluid pressure in region 3H exceeds the weight induced pressure in piston region 3G.

When the second tooling member is impacted, piston region 3G is induced to a pressure greater than gas region 3K and is overbalanced. Valve piston 353 moves downward opening passage for piston region fluid 3G to flow into accumulator region 3H. As secondary piston 350 moves downward, accumulator piston 352 also displaces downward. If the secondary piston comes to rest before entering stopping cushion 3GG in valve piston 353, piston region 3G immediately reverts to the same pressure as in region 3H, and this pressure starts slowly returning the second tooling member upward. Simultaneously, however, the force now acting upwards on valve piston 353 equals gas region 3K pressure minus accumulator 3H pressure times the area of diameter 3T. Encountering low inertial resistance, this force (in a rapid check valve action) shifts piston valve 353 upwards and accumulator piston 352 downwards until regions 3H and 3G are again isolated, leaving the second tooling member little time to gain upward velocity before halting such motion. If the secondary piston downward motion after a blow stops inside cushion 3GG, then the second tooling member along with valve piston 353 both slowly rise together the short distance until valve piston 353 is seated and further upward motion is checked.

Returning the second tooling member 302 upwards to forming position is done in the usual manner by bypassing the check valve means upon signal from the operator. By-pass valve V317 is opened permitting accumulator region 3H pressure to act upwards on the secondary piston in piston region 3G. Again a pointer piston can be used in conjunction with the third secondary chamber arrangement to control the second tooling member forming position.

As shown accumulator hydraulic region 3H is cut off from communication with piston region 3G by metal to metal seating of the valve face of piston 353 against its valve seat 353A in chamber plate 355. Retaining a resilient material on either of the mating surfaces at this place insures a more effective pressure seal. Such material, however, may not be sufficiently resistant to the erosive effects of hydraulic fluid flow during the second tooling member downstroke.

Fourth Embodiment

FIG. 14 shows a fourth secondary chamber arrangement built into and supported by a common frame assembly which in turn rests on gas cushions above support pistons 487. Reaction for stopping second tooling member motion after a forming blow is transmitted by cross member 456 and dowels 494 to the side frames which take the load inertially. The advantage of supporting the secondary chamber in this manner is that downward loading on the foundation can be reduced.

The operation of the fourth secondary chamber arrangement is not affected by the mounting arrangement; it could have been shown as a separate assembly resting directly on the foundation. Conversely, the other embodiments of the secondary chamber could have been shown built into the common frame assembly without affecting their operation either.

The fourth secondary chamber arrangement has a valve piston 453 which functions as a valving means similarly to member 353 in the third embodiment. When secondary piston 450 is propelled downward, valve piston 453 unseats downward from its valve seat surface 453A, opening a path for piston region 4G hydraulic fluid to flow into reservoir 4H. Unlike all the three previous embodiments, however, reservoir 4H is not pressurized by an accumulator piston, but is connected instead to atmosphere by vent 474 and drains directly into the main reservoir in the external hydraulic system. Elimination of the accumulator piston simplifies the secondary chamber arrangement and, as will be explained, can permit greater second tooling member downward travel following lower energy forming blows. In this arrangement, however, the secondary chamber is no longer able to store second tooling member kinetic energy in an accumulator for use in returning the second tooling member to forming position. An external power input such as Pump P3 is required to pump hydraulic fluid back into piston region 4G upon signal and displace the second tooling member upwards.

The valve face of piston 453 can be held seated by any of several methods in order for the second tooling member to be raised and maintained at forming position. The most elementary method uses a fixed mechanical or gas spring. For example, consider region 4K disposed in crossmember 456 below valve piston 453 as confining a gas spring whose pressure can be set high enough to hold the valve piston seated against the pressure induced in piston region 4G by the second tooling member weight. As the second tooling member is propelled downward by impact, piston region 4G intensifies to a pressure which acting on the valve face of piston 453 overbalances region 4K gas spring force, and valve piston 453 unseats. Orifice pressure drop as piston region 4G hydraulic fluid exhausts across the valve seat surface 453A into reservoir region 4H causes back pressure in piston region 4G. This back pressure balances the valve piston unseated until the second tooling member is stopped, causing back pressure to drop off in the piston region, and the gas spring in region 4K again seats valve piston 453, locking piston region 4G off from exhaust to atmosphere reservoir 4H.

Throughout the second tooling member downstroke, this piston region back pressure to unseat valve piston 453 resists the motion with a force equal to one and one-third or more of the second tooling member weight, so that similarly to the other embodiments using accumulator pistons, the second tooling member kinetic energy and velocity are absorbed prematurely by the yielding secondary chamber after low energy blows before the second tooling member has moved down full stroke. However, since no accumulator pressure gas is in this case being compressed and charged with energy to power the second tooling member return to forming position, the back pressure produced in piston region 4G by flow across the valve piston seat serves no purpose.

FIG. 14 indicates a method of controlling valve piston 453 which permits the piston region hydraulic pressure to drop instead of increase when the second tooling member is impacted and thus releases the second tooling member to the force of gravity causing it to move down full distance after low energy level forming blows. Consider region 4K to be pressurized sufficiently with valve control gas or control fluid to hold valve piston 453 seated while the second tooling member is up at its forming position. Gas region 4L in pilot control accumulator 459 is fully expanded and at a very low pressure. Now at the exact same instant the machine is signaled to stroke, control valve V425 is also signaled to open, permitting region 4K valve control gas to expand into region 4L and drop quickly to a very low pressure. Simultaneously, the second tooling member is impacted and imparted with downward kinetic energy. As the second tooling member now moves downward, valve piston 453 is urged towards its valve seat surface 453A by the suddenly reduced force of control gas 4K, which in turn creates only a very nominal back pressure in piston region 4G. The back pressure force acting on the second tooling member as it moves downward is far less than the second tooling member weight, so that the second tooling member with the help of gravity actually gains kinetic energy during downward motion until it enters the secondary stopping cushion 4GG provided in valve piston 453.

To return the second tooling member to forming position, valve piston 453 must first be raised against its valve seat surface 453A.

Valves V425 and V417 are closed, and pump P4 begins pumping hydraulic fluid into pilot control accumulator 459, displacing piston 452 to the right of the position shown. Control gas in region 4L is displaced from the accumulator past check valve 422 back into region 4K until that region has enough control gas pressure to lift the second tooling member and thereby reseat valve piston 453 on which the second tooling member is resting. This done, pump P4 stops and upon signal Pump P3 starts pumping fluid into the piston region now closed off by the seated valve piston 453, and the second tooling member is displaced upwards. Valve V417 reopens and the little control gas remaining in region 4L expands, displacing the hydraulic fluid from pilot accumulator 459 in preparation for another second tooling member down stroke.

Pilot accumulator 459 raises and lowers the pressure in region 4K without any loss of valve control gas. If pressure gas is in ready supply, such as a large capacity shop air system, region 4K pressure can be raised by charging it from the supply source and lowered by exhausting region 4K to atmosphere during each machine cycle.

Region 4J is confined in cross member 456 surrounding the outside diameter of valve piston 453. Seal means 465 prevents its communication with reservoir 4H. If region 4J is charged with a quantity of gas, the pressure acts down on valve piston 453 over the area between the inside diameters of seals 463 and 465. If this downward pressure force is greater than the pressure force of region 4K after region 4K control gas is allowed to expand into region 4L when the machine strokes, then valve piston 453 unseats downward independently of hydraulic pressure in piston region 4G, and backpressure resistance in the piston region is zero as the second tooling member is propelled downward,

being boosted in that motion by the full force of gravity.

The addition of control valve V426 provides means which not only eliminates back pressure, but also insures that valve piston 453 unseats instantaneously when the second tooling member is impacted. Assume regions 4J and 4K to have been charged with gas in the manner already discussed. Assume that the second tooling member is in its down position and that valve piston 453 is unseated. Assume also that valve V426 is in the closed position shown. Valve piston 453 is reseated by first increasing control gas region 4K to a high pressure using pilot accumulator 459 or other means. In the seated position the valve piston's flange 15 also seats against seal means 464. Valve V426 now opens exhausting the negligible quantity of gas trapped between seals 463 and 464; this causes region 4J pressure to act upwards on the valve piston over the area between seal 464 and the inside surface of seal 465. 20 This force clamps the valve piston in the seated position as region 4K pressure is now reduced by expansion into region 4L or by exhaust to atmosphere. Valve piston 453 is held seated by this clamping force while pump P3 in response to signal pumps fluid into the 25 closed off piston region 4G, raising the second tooling member to forming position. Before the machine strokes, valve V426 shifts closed again. When the second tooling member is impacted, piston region hydraulic pressure intensifies to a level sufficient to overbalance the region 4J clamping force on valve piston 453, causing the valve flange to break contact with seal 464. The force on the valve piston is instantly reversed as region 4J pressure is freed to act downward over the area between seals 463 and 465 and valve piston 453 instantly unseats. Impact pad 4KK absorbs the shock of the rapid unseating. This last method of valve piston control bears features in common with rapid pneumatic actuation means previously described in B. I. Brown 30 U.S. Pat. No. 3,093,118.

Another valve piston control method also applicable to this secondary chamber arrangement is shown in FIG. 5 of J. B. Ottestad Pat. No. 3,039,292. As with the last described method of control, the Ottestad valve piston is unseated by a pulse of over-pressure. Also back pressure is zero during second tooling member descent using the Ottestad valve piston. But satisfactory means for reseating the valve piston which would be amenable to production cycling has not been described in the Ottestad patent.

The fourth secondary chamber arrangement returns the second tooling member to forming position at generally slower speed than do the previous embodiments which use accumulator piston drives, because the up-velocity in this case is limited by the displacement capability of pump P3. Also, the accuracy with which the second tooling member is raised to a desired forming height is reduced because the volume of fluid pumped into the piston region during elevation cannot be adjusted beforehand. The height of the second tooling member at forming position depends on accurate control of the elevating pump shut off with limit switches or other means. Great care must be taken to assure consistent return to the desired forming positions.

Fifth Embodiment

The fifth embodiment machine shown in FIG. 15 has a common frame assembly again suspended on gas

cushions above support pistons 587 in identical manner to the second embodiment machine. The primary and secondary chambers, however, incorporate additional variations within the scope of the invention.

The fifth embodiment of the primary chamber means is a combination of primary stopping from the second embodiment and reset means from the third arrangement. A stopping cushion is confined in region 5C below primary piston head 504 within inner cylinder 515. Seal means 527 blocks communication to the chamber exterior. Due to the presence of cushion gas region 5C, the acceleration-stopping thrust characteristic for this primary chamber assembly is essentially the same as the solid line curve, F201, shown in FIG. 10. As in the third embodiment, inner reset piston 505 reciprocates in the bore of inner cylinder 515 just above primary piston head 504. Inner piston region 5E is confined within that bore between the reset piston and the primary piston head. The method of communicating inner piston region 5E with the external hydraulic system has been altered slightly in this embodiment. In place of a delivery tube attached to the inner reset piston and directed upward therefrom as in FIG. 13, delivery tube 522 is attached to head closure plate 512 and extends downward through seal means 537 in the reset piston. A drilled passage in closure plate 512 connects the delivery tube with the external hydraulic system. Primary pressure gas region 5A is confined outside inner cylinder 515 and inside cylinder 513 and communicates through ports at the upper end of the inner cylinder with inner reset piston 505.

Reviewing its operation, the fifth embodiment primary chamber as shown is in the ready to stroke condition. Hydraulic actuation fluid is trapped in region 5E by external valve means. Temporary region 5B, confined between reset piston 505 and head closure plate 512, is depressurized to atmosphere by valve V512. Reset seal 510 blocks primary gas pressure in region 5A from entering region 5B. First tooling member 501 and inner reset piston 505 are clamped against closure plate 512 by the stopping cushion gas in region 5C acting on the underhead surface of the primary piston head between diameters 5R and 5N. A first tooling member stroke is initiated when stroke initiation valve V511 opens pressurizing region 5B to overbalance the region 5C gas force acting upwards. The reset piston moves down, pushing the first tooling member below it until reset seal 510 is cleared. Primary region 5A pressure now acts directly over the upper face area of the inner reset piston, accelerating the reset piston and primary piston head downward until the limiting balance or rest point is reached.

Once the first tooling member 501 and inner piston 505 have come to rest at the limiting rest position, the reset procedure begins in the following way. The external system pumps hydraulic actuation fluid through delivery tube 522 into region 5E, raising inner reset piston 505 towards head closure plate 512. As the reset piston moves up compressing primary gas region 5A, the primary piston head moves downward slightly in order to maintain pressure balance with stopping gas region 5C. When the reset piston has butted against head closure plate 512 and engaged reset seal 510, region 5B thus temporarily created is depressurized to atmosphere by depressurizing valve V512. Inner piston region 5E is now opened to a low pressure reservoir in the external hydraulic system. Cushion region 5C exerts a force raising

first tooling member 501 and displacing actuation fluid from region 5E. As the first tooling member rises, it can be halted at any stroke height desired by operator signal to the external valve means which controls region

5E exhaust to the low pressure reservoir. The first tooling member stroke can be initiated from any height above limiting rest position, its stroking energy being greater the further it is reset upwards before stroking.

It should be noted that the reset seal in embodiments 10 3 and 5 need not have been shown as a bonded member positioned in female relation to the piston it engages. Instead the reset seal could have been a radial ring carried in a groove around the upper end of the inner piston in much the same fashion as reset seal 10 is carried 15 on the periphery of face flange 23 is illustrated in FIG. 4. In FIG. 4 engagement wall 47 is set on top of the primary piston head. Following the design to the third and fifth embodiments, a cylindrical engagement wall would have to be incorporated almost as shown set in 20 the head closure surface except that no seal would be bonded thereto. One area of concern in using a reset seal mounted radially on an inner piston in embodiment three or five is that after the seal clears the closure engagement wall as a stroke is initiated, the seal 25 then is required immediately to enter the inner cylinder 315 or 515 as the stroke proceeds. To make this entry without injury, the seal cannot be out of its groove or at all exposed to hitting the end face of the inner cylinder. Thus the precautions discussed earlier for preventing the seal from blowing out of place during stroke initiation are doubly important in those embodiments.

The fifth secondary chamber system present in FIG. 15 is an inverted arrangement in which secondary piston 550 is fixed stationary to the foundation while piston region 5G is confined within and travels with second tooling member 502. When the second tooling member is impacted, the force exerted on secondary piston 550 by the secondary chamber arrangement reverses from a force supporting the second tooling member weight to a force which urges the second tooling member downward; regardless of mechanical friction or how little kinetic energy is imparted to the second tooling member by impact, the second tooling member bottoms in its stopping cushion 5GG after each blow. 40 45 This reversal of force exerted by the secondary chamber system is a particular advantage in large scale machines where the second to first tooling member mass ratios are greater than 2 to 1 and also in small scale machines where secondary piston packing and seal friction inhibit the separation downward of the lower tooling. The arrangement also incorporates a new control method for seating and unseating the valve piston member. Similarly to the fourth embodiment this fifth secondary chamber arrangement relies on an external 50 hydraulic power means to return the second tooling member to forming position.

Secondary piston shaft 550 has sealed reciprocating entry through entrance means 560 at the bottom of second tooling member 502. Secondary piston head 551 is in sealed reciprocating contact with chamber cylinder 557. Hydraulic fluid from the external system is delivered into piston region 5G above secondary piston head 551 through a drilled passage up the center of that piston. The cavity in the second tooling member which receives cylinder 557 and secondary piston 550 has a reduced diameter pocket 5GG at its upper end; this pocket in fitted male-female engagement with the sec-

ondary piston head 551 provides the secondary stopping means. Check plate 554 retained at the upper face of secondary piston head 551 prevents loss of stopping pressure from cushion pocket 5GG during the second tooling member stopping. Valve piston 553 is a ring shaped member received in the annular space surrounding the piston region 5G above closure plate 556. Valve piston 553 is permitted a short vertical stroke in that space. In its bottom position the valve face of piston 553 seats against valve seat surface 553A in closure 556 at diameter 5W. Hydraulic region 5H is confined below the valve face of piston 553 and above closure 556 and is vented to an external reservoir. In the position shown region 5H is isolated from piston region 5G hydraulic fluid by the seating of valve piston 553 against seat 553A. Valve spring gas region 5K1 is confined in the second tooling member above valve piston 553 between diameters 5V and 5X. Secondary pressure gas region 5K2 is confined by chamber cylinder 557 between the underhead surface of secondary piston head 551 and piston entrance 560. Region 5K2 is prevented from communicating with piston region 5G hydraulic fluid by piston seal means 561 and from communicating with the chamber exterior by seal means 562. Regions 5K1 and 5K2 are in constant pressure communication through the interdrilled passage shown. Region 5J is confined in the second tooling member above valve piston 553 between diameters 5X and 5Z. Region 5J is permanently vented to atmosphere through drilled passages. Seal means 563 and 564 isolate region 5K1 from regions 5G and 5J respectively. Seal means 565 isolates hydraulic region 5H from atmospheric region 5J. Hydraulic region 5H and gas regions 5K1 and 5K2 are communicated to the external control circuit by flexible hose or other means.

Region 5H as illustrated in FIG. 15 is always in communication with an external low pressure reservoir through flow control valve V522, and when valve piston 553 is seated as shown, region 5H is at approximately atmospheric pressure. When the second tooling member is at forming position, piston region 5G is pressurized by the weight of the second tooling member plus the force of secondary pressure gas region 5K2 acting down on the piston entrance 560. This piston region hydraulic pressure acts upwards on the valve face of piston 553 over the area between diameters 5V and 5W. In order for the valve piston 553 to remain seated against this piston region pressure force:

$$pr_{5K1} \left(\frac{ar_{5X} - ar_{5V}}{ar_{5W} - ar_{5V}} \right) > pr_{5K2} \left(\frac{ar_{5U} - ar_{5T}}{ar_{5V}} \right) + \frac{W_2}{ar_{50}}$$

where:

pr_{5K1} and pr_{5K2} are the pressures of valve spring gas 551 and secondary pressure gas 5K2, ar_{5X} , ar_{5W} , ar_{5V} , and ar_{5T} are the areas respectively of diameters 5X, 5W, 5V, 5U, and 5T, and where W_2 is the weight of the second tooling member.

Since regions 5K1 and 5K2 are in pressure communication:

$$pr_{5K1} = pr_{5K2}$$

and the secondary piston area ratio,

$$\left(\frac{ar_{5V} - ar_{5T}}{ar_{5V}} \right)$$

must be less than the valve piston area ratio,

$$5 \quad \left(\frac{ar_{5X} - ar_{5V}}{ar_{5W} - ar_{5V}} \right) - \frac{W_2}{(pr_{5K1}) (ar_{5V})}$$

in order for valve piston 553 to stay seated while the second tooling member waits at forming position.

When the second tooling member is impacted, pressure in piston region 5G instantly intensifies unbalancing and unseating valve piston 553; once this occurs, piston region pressure communicates into region 5H and acts upwards on the valve face of piston 553 over the entire area between diameters 5V and 5Z. Hydraulic fluid at this point exhausts from regions 5G and 5H through valve V522, but at an insufficient rate to permit valve piston 553 to reseat as the second tooling member moves downward and the secondary piston displaces into the secondary chamber. After the initial pressure intensification to first unseat valve piston 553, the piston region hydraulic pressure necessary to continue displacing valve piston 553 away from its seat 553A drops inversely to the increase in valve face area over which the piston region fluid is released, e.g., by the factor:

$$30 \quad \left(\frac{ar_{5W} - ar_{5V}}{ar_{5Z} - ar_{5V}} \right)$$

where ar_{5Z} is the area of diameter 5Z.

For the proportions used in FIG. 15 this factor is approximately $\frac{1}{3}$, and the pressure in piston region 5G drops to $\frac{1}{3}$ the initial unseating pressure once the second tooling member is set in motion. As a result of this drop in piston region pressure the net force exerted by the secondary chamber arrangement on secondary piston head 551 equals:

$$40 \quad pr_{5K1} \left(\frac{ar_{5X} - ar_{5V}}{ar_{5Z} - ar_{5V}} \right) (ar_{5U}) - pr_{5K2} (ar_{5V} - ar_{5T})$$

or:

$$45 \quad pr_{5K1} (ar_{5U}) \left[\left(\frac{ar_{5X} - ar_{5V}}{ar_{5Z} - ar_{5V}} \right) - \left(\frac{ar_{5U} - ar_{5T}}{ar_{5U}} \right) \right]$$

50 and this net force acts in addition to the second tooling member weight to urge the secondary piston into piston region 5G so long as the secondary piston area ratio,

$$\left(\frac{ar_{5U} - ar_{5T}}{ar_{5U}} \right)$$

is greater than the valve piston area ratio,

$$60 \quad \left(\frac{ar_{5X} - ar_{5V}}{ar_{5Z} - ar_{5V}} \right)$$

65 This net secondary chamber force together with the second tooling member weight accelerates the second tooling member positively downward until secondary stopping cushion 5GG engages the secondary piston head 551 and brings the second tooling member to a halt.

After the second tooling member is halted in its down position, the force of valve spring gas region 5K1 returns valve piston 553 downward displacing fluid from hydraulic regions 5H and 5G through exhaust valve V522 until valve piston 553 is again reseated. And the system is prepared for repumping the second tooling member back up to its forming position.

If chamber cylinder 557 together with secondary pressure gas region 5K2 is eliminated from the fifth secondary chamber arrangement, then secondary piston 550 becomes a simple plunger similar to the previously described secondary pistons, and the secondary chamber can no longer accelerate the second tooling member downwards. Such an altered fifth version system produces an effect on the second tooling member similar to the fourth embodiment secondary chamber, namely, that upon impact back pressure in piston region 5G is reduced to $\frac{1}{3}$ the valve piston unseating pressure, thereby reducing resistance to downward motion of the second tooling member sufficiently and releasing the second tooling member to the force of gravity sufficiently so that the second tooling member moves down full distance into stopping cushion 5GG. conversely, the fourth embodiment secondary chamber can be arranged with a secondary pressure gas region confined surrounding the shaft portion of secondary piston 450 and disposed to urge secondary piston 450 into piston region 4G, and piston 450 can be attached rigidly to the second tooling member 402 and thereby able to transmit secondary chamber thrusts urging the second tooling member to accelerate downward after a forming blow similarly to the fifth secondary chamber arrangement.

FIG. 15 shows a method of returning the second tooling member to forming position which is applicable to both the fourth and fifth embodiments of the invention so long as piston region back pressure during downstroke is minimal and the second tooling member consistently bottoms in its stopping cushion 5GG after each blow. The method provides speed and accuracy in raising the second tooling member to any selected forming height. Cylinder assembly 577 and pointer piston 576 combine functions as a second tooling member forming position selector and a gas pressurized accumulator — an accumulator charged, however, by external pump P5 and not by the downward motion of the second tooling member as in the first three embodiments. Piston 576 has the same face area as secondary piston head 551. Accumulator gas region 5K3 is in communication with valve spring gas region 5K1 above valve piston 553. After the machine strokes, valve V517 closes and pump P5 begins pumping hydraulic fluid from the external system past check valve V520 into region 5L, raising pointer piston 576 from its down position. As piston 576 moves up, energy is stored by compressing accumulator gas region 5K3. When the rod pointer attached to piston 576 reaches the height to which the operator wants the second tooling member to move, pump P5 is stopped. After valve piston 553 is seated against valve seat 553A, the operator raises the second tooling member by signalling valve V517 to open. The gas pressure in region 5K3 forces pointer piston 576 back downward, displacing fluid from region 5L past check valve V521 up through secondary piston 550 into piston region 5G. The second tooling member rises the same distance that pointer piston 576 descends and stops when piston 576 reaches

bottom stroke, exactly when the predetermined volume of fluid has been displaced into piston region 5G. Because the second tooling member moves upward under the power of the accumulator gas spring 5K3, its up speed is greater than if driven directly by pump P5. The second tooling member up velocity is adjusted with flow valve V518.

While the second tooling member is returning to forming position, secondary chamber region 5G is pressurized by accumulator gas region 5K3, and this pressure again is acting upwards on the valve face of piston 553 over the area between diameters 5W and 5V. Simultaneously the pressure of region 5K3 is in communication with valve gas region 5K1 and acts down on valve piston 553 over the larger area between diameters 5X and 5V. By this precaution valve piston 553 is held positively seated, no matter how high the gas pressure in accumulator 577 is set to raise the second tooling member.

A safety feature which can insure that the second tooling member does not move up while the operator is working in the die area of the machine consists of opening valve V519 while the second tooling member is in the down position. Should valve V517 accidentally open and the accumulator discharge fluid into the secondary chamber, regions 5G and 5H will be in communication, and valve piston 553 will unseat upwards in place of the second tooling member up motion. Also, if the second tooling member is already up at forming position and it is desired to return it downward without striking a forming blow, valve V519 can be opened unseating valve piston 553 which automatically causes the second tooling member to move downward and displace piston region fluid into vented region 5H.

A simplification of valve piston 553 can be obtained by eliminating seal means 564 and by allowing valve spring gas region 5K1 to act down on the valve piston over the full area between diameters 5Z and 5V. If this is done, however, region 5K1 must not be permitted communication with regions 5K2 or 5K3, but must be separately set at a lower pressure in order to exert the proper seating force on valve piston 553.

Additional secondary piston chamber variations follow logically from the five embodiments presented in the figures, and all such variations are to be considered within the scope of this patent. For example, all of the first four secondary chambers can be built attached to and moving with the second tooling member in the same fashion as the fifth embodiment machine. Stationary secondary pistons can be adapted for bottom entrance into moving secondary chamber means where the hydraulic stopping cushions are presently shown, and the stopping cushions can be relocated in upper closures which confine piston regions within the moving second tooling members. The reverse procedure applied to the fifth embodiment secondary piston chamber produces a secondary piston which moves with the second tooling member and reciprocates into a stationary secondary chamber.

Another manipulation which does not alter the secondary piston chamber's functions is to invert the motion of the valve piston members within the chambers. The valve piston 353 in the third embodiment can be replaced with an annular valve piston which seats downward and along with a surrounding accumulator piston is gas pressurized from above; the secondary stopping cushion 3GG in this instance can be located

directly in chamber closure 356. In similar fashion valve piston 453 can be inverted without altering the control gas means used to seat it. The fifth embodiment valve piston can also be arranged to seat upwards, and if confined in a stationary secondary chamber separate from the second tooling member, valve piston 553 can be adapted with a stopping cushion 5GG after the fashion of pistons 353 and 453 without altering its manner of reducing back pressure when a forming blow is struck.

Another approach involves confining piston regions G and accumulator regions H in separate chambers connected by piping means. The piston region chamber adapted with hydraulic stopping cushion means receives the secondary piston directly below the machine, while the accumulator piston means or the various valve piston means described are confined in remotely located control chambers.

The inversion manipulation can also be applied to all the embodiments of the primary piston chamber. Each embodiment can be inverted almost intact, anchoring the inverted primary piston shafts to a cross beam at the upper end of a common frame assembly, and attaching the primary chambers, including reset and primary stopping means, etc., to the moving first tooling member proper. In the case of the third and fifth embodiment primary chambers, hydraulic fluid can conveniently be communicated into inner piston regions 3E or 5E through the inverted primary piston shaft. In the case of the first and second embodiments, a delivery tube arrangement would most likely have to be used to deliver hydraulic actuation fluid into regions E located by this inversion within the first tooling member proper.

Returning now to one of the major advantages of this invention, die area has been limited in the previous high velocity impact type forming machines for several reasons. In many of the previous machines the lower tooling member is built as an integral unit with the side frames and upper chamber. And since this whole unit is subjected to impact forming loads, it must be built as compactly and with as small a die area tolerable in order to minimize inertial stresses. Also, many of the previous machines in this art are built with jacking pistons and upper to lower tooling member drive pistons and linkages which take up valuable space in the tooling area of the machines.

In the present invention all piston chamber means are located either above the first tooling member or below the second tooling member, leaving the tooling areas clear solely for tooling. Also the second tooling member of this machine is a simple block shape; a large upper face is allotted for lower tooling without risk of inertial damage.

In this invention the adjustable stroke energy capability, the large die areas, and high off center loading capabilities combine to make multiple station tooling practical, permitting such die saving procedures as breaking scale, preforming, fullering and blocking. Adding to this the elimination of abusive restrike and protracted exposure to heat, the die life picture for this invention is much improved over the previous machines in this art.

The embodiments of the invention in which an exclusive property or privilege is claimed are defined as follows:

1. A forming machine comprising in combination,

a first tooling member,
a second tooling member,
a common frame,

said first and second tooling members being adapted to reciprocate along a common axis on said machine,

said first and second tooling members provided with means for attaching forming dies to their adjacent surfaces,

primary piston chamber means arranged together with said first tooling member confining primary pressure gas which through expansion is adapted to urge said first tooling member in direction toward said second tooling member,

primary stopping means limiting expansion of said primary pressure gas and limiting distance of travel of said first tooling member in direction toward said second tooling member without disabling said machine whereby an end of stroke position for said first tooling member and a corresponding normal expanded condition of said primary pressure gas are determined independently of second tooling member motion or position,

reset means adapted to compress said primary pressure gas from said normal expanded condition and cause said first tooling member to move from said end of stroke position in direction away from said second tooling member to a beginning stroke position,

stroke initiating means adapted to release said primary pressure gas from said compressed condition and said first tooling member from said beginning stroke position whereby said primary pressure gas propels said first tooling member against said primary stopping means and said primary stopping means operates to limit rest position and whereby said first tooling member is actuated to strike a forming blow against said second tooling member positioned for forming,

secondary piston chamber means arranged in association with said second tooling member, fluid control means adapted to regulate fluid in said secondary piston chamber means whereby said secondary piston chamber means is caused only in response to operator controlled signal to move said second tooling member along said common axis in direction toward said first tooling member to forming position and whereby said secondary piston chamber means is caused to maintain said second tooling member at said forming position,

said fluid control means adapted to allow said secondary piston chamber means to yield to said induced second tooling member motion and sustain said motion after a single forming blow while first tooling member motion is being curtailed by said primary stopping means whereby said second tooling member is caused to separate completely away from said first tooling member after a single forming blow,

secondary stopping means limiting the distance said second tooling member may travel in direction away from said first tooling member after a single forming blow without disabling said machine.

2. The forming machine recited in claim 1 wherein said primary piston chamber means having respectively at its opposite ends shaft closure means and head closure means,

primary piston means having sealed reciprocating entry to within said primary chamber means through said shaft closure means,

said reset means comprising opposed piston means having sealed reciprocating communication to within said primary chamber means from head closure means and situated in opposed relation to said primary piston means within said primary chamber means, the interior ends of said opposed piston and primary piston means disposed facing each other, 10

said primary pressure gas confined in said primary chamber means communicable with the interior ends of opposed piston means and primary piston means,

said reset means comprising hydraulic actuation means adapted to urge said oppose piston means into said primary chamber means toward said primary piston means while said first tooling member is at limiting rest position whereby primary pressure gas is compressed from its normal expanded condition until the interior end face of said opposed piston means engages the interior end face of primary piston, 20

said rest means comprising depressurizing means adapted to reduce the gas pressure between said engaged piston faces, seal means cooperating to isolate said depressurized piston faces from primary pressure gas whereby the net thrusts on primary piston and opposed piston are altered in such manner that upon release of said hydraulic actuation means said piston means remain engaged and move together and said primary piston means retracts into said primary chamber means and thereby moves said first tooling member from limiting rest position in direction away from said second tooling member until stopped at any stroke position by locking said hydraulic actuation means, 25

said stroke initiation means operating upon signal to increase pressure on said engaged piston faces and thereby urge primary piston means to disengage from opposed piston means and disengage seal means whereby primary pressure gas is released to the full end face of said primary piston producing a sudden thrust urging primary piston outward from said primary chamber means and whereby through expansion of primary pressure gas said first tooling member is urged from stroking position in direction toward said second tooling member. 30

3. The forming machine recited in claim 1 wherein secondary piston shaft means adapted for sealed reciprocating motion into and out from said secondary chamber means through piston entrance means, 50

secondary piston head means in rigid attachment to said secondary piston shaft means within said secondary chamber means and disposed in sealed reciprocating contact within chamber cylinder means, said secondary piston head means having greater diameter than said secondary piston shaft means, 55

secondary pressure gas confined in said secondary chamber means and disposed communicable within said chamber cylinder means and around said secondary piston shaft means between the underhead surface of said secondary piston head means and said piston entrance means whereby, when a single forming blow induces second tooling member motion in direction away from said first

tooling member, said secondary piston shaft means is released to the thrust of said secondary pressure gas which acting on the underhead surface of said secondary piston head means urges secondary piston shaft means to move into said secondary chamber means and thereby causes second tooling member motion following a single forming blow to continue and be sustained until said second tooling member has adequately separated away from said first tooling member.

4. The forming machine recited in claim 1 wherein said first tooling member disposed vertically above said second tooling member, said first and second tooling members adapted for reciprocating motion along a common vertical axis,

said primary piston chamber means embodying closure means rigidly connected to said common frame.

5. The forming machine recited in claim 4 wherein said common frame is supported with respect to a fixed foundation by flexible spring means.

6. The forming machine recited in claim 5 wherein said flexible spring means constituting expansible gas cushion chambers,

said gas cushion chambers being supported to said fixed foundation by hydraulic piston chamber means whereby the vertical position of said common frame is hydraulically adjustable without necessity of varying the quantity of gas in cushion chambers.

7. The forming machine recited in claim 1 wherein said primary piston chamber means having respectively at its opposite ends shaft closure means and head closure means,

primary piston shaft means aligned in the direction of said common axis and having sealed reciprocating entry to within said primary chamber means through shaft closure means,

primary piston head means rigidly connected to said primary shaft means within said primary chamber means,

said primary chamber means having inner cylinder means, said primary piston head means disposed in sealed reciprocating contact with the inside wall of inner cylinder means,

said primary pressure gas being confined within said primary chamber means outside and surrounding said inner cylinder means and communicable to within said inner cylinder means through porting means at head closure means whereby primary pressure gas is capable of exerting a force on said primary piston head means and by expansion capable of urging said primary piston shaft out from said primary chamber means whereby said first tooling member is urged from stroke position in direction toward said second tooling member.

8. The forming machine recited in claim 7 wherein said inner cylinder means constituting a small inner cylinder and a large inner cylinder, small cylinder having a smaller inside diameter than large cylinder, small inner cylinder arranged aligned with and connected to large inner cylinder with said large cylinder disposed toward the shaft closure end of said primary chamber means, small inner cylinder means disposed toward said head closure end, primary piston head disposed in sealed reciprocating contact within small inner cylinder means,

said primary stopping means constituting collar piston means disposed within large inner cylinder surrounding and in sealed reciprocating contact with primary piston shaft between shaft closure means and the underhead surface of primary piston head means, collar piston disposed at its outer diameter in sealed reciprocating contact with large inner cylinder means, said collar piston means having greater face area than primary piston head, an intermediate region confined within said large and small inner cylinder means surrounding primary piston shaft means between the underhead surface of piston head and collar piston means, intermediate region sealingly isolated from primary pressure gas and adapted to be filled with hydraulic fluid, 10 said primary pressure gas confined outside said large and small inner cylinder means and directed to within small inner cylinder through porting means at said head closure means and directed to within large inner cylinder means through porting means 15 at shaft closure means and thereby directed to exert a force on collar piston means whereby hydraulic fluid in intermediate region is pressurized when said first tooling member is propelled from stroke position toward said second tooling member 20 and whereby outward motion of primary piston shaft means from said primary chamber means is resisted by a nominal force of said fluid pressure in intermediate region acting on said underhead surface of primary piston head until said collar piston means engages said underhead surface and begins moving with primary piston head whereby intermediate region commences expanding in volume and thus loses fluid pressure and the force resisting said 25 outward motion of primary shaft suddenly increases to the force of primary pressure gas acting on the full face of collar piston means whose face area is greater than the full face area of primary piston head and whereby the resulting net force resists and stops further outward motion of primary 30 piston shaft from said primary chamber means and causes said first tooling member together with piston shaft and collar piston means to move to a limiting rest position at which said fluid in intermediate region is again pressurized by primary pressure gas in its most expanded condition acting on collar piston and at which collar piston means remains 35 engaged with primary piston head.

9. The forming machine recited in claim 8 wherein 40 replenishment means adapted to keep intermediate region completely occupied and supplied with low pressure fluid when intermediate region expands following engagement of collar piston with primary piston head during outward movement of said primary piston shaft means, check valve means preventing replenishment fluid supplied into intermediate region during its expansion from flowing back out of said intermediate region faster than at a restricted rate whereby once stopped after a forming blow primary piston shaft and 45 collar piston return with controlled speed inward into said primary chamber means until reaching limiting rest position at which position intermediate region has its original volume,

primary piston head means and collar piston means arranged to have close clearance male-female engagement whereby intermediate region fluid is trapped between said members during engagement

and thereby provides hydraulic cushioning which prevents damage to said two members.

10. The forming machine recited in claim 1 wherein 5 said primary piston chamber means having respectively at its opposite ends shaft closure means and head closure means,

primary piston means having sealed reciprocating entry to within said primary chamber means through said shaft closure means,

said reset means comprising inner piston means adapted to reciprocate within said primary chamber means in a common direction with primary piston means between the interior end of said primary piston means and head closure means,

an inner piston region confined between inner piston means and said primary piston means,

said primary pressure gas confined within said primary chamber means and disposed communicably with the face of inner piston means adjacent to head closure means, said primary pressure gas isolated from inner piston region,

said reset means comprising hydraulic power means adapted to supply fluid into said inner piston region and thereby displace inner piston away from primary piston while said first tooling member is at limiting rest position and thereby compress said primary pressure gas from its normal expanded condition until inner piston means engages head closure surface,

said reset means comprising depressurizing means adapted to reduce the gas pressure between the engaged surfaces of inner piston and head closure with seal means cooperating to isolate said depressurized surfaces from said primary pressure gas whereby the net thrusts on inner piston means and said primary piston means are altered in such manner that upon release of said fluid from inner piston region, said inner piston means remains engaged with head closure while primary piston means retracts into said primary chamber means thereby causing said first tooling member to move from limiting rest position in direction away from said second tooling member until stopped at any stroke position by locking any remaining fluid in inner piston region,

said stroke initiation means operating upon signal to increase pressure on said engaged piston and closure surfaces thereby urging inner piston means away from the surface of closure means disengaging seal means whereby said primary pressure gas is released to act on the face of inner piston producing a sudden thrust urging said inner piston together with remaining fluid in inner piston region and said primary piston to move together and propelling said primary piston means outward from said primary chamber means whereby said primary pressure gas expands and said first tooling member moves from stroke position in direction toward said second tooling member.

11. The forming machine recited in claim 10 wherein 60 said seal means comprises a ring shaped member of resilient composition carried in a groove around the cylindrical outside wall of said inner piston means and disposed adjacent the end of said inner piston means 65 which engages said head closure surface whereby during said engagement said seal means is held sealingly against a mating cylindrical engagement wall set in said

head closure surface whereby said seal means and co-operating engagement wall form a surrounding boundary which isolates the engaged surfaces of said inner piston and head closure from communication with primary pressure gas.

12. The forming machine recited in claim 10 wherein said primary piston chamber means being constructed with cylinder means,

primary piston head means in rigid attachment to primary piston shaft means within said primary chamber means and disposed in sealed reciprocating contact with the inside wall of said cylinder means, said inner piston means also disposed in sealed reciprocating contact with the inside surface of said chamber cylinder means, said inner piston region confined in said cylinder between primary piston head and inner piston means, said inner piston region communicable with external hydraulic power and control means through delivery tube means attached to head closure means and extended into said primary chamber means passing sealingly through said reciprocating inner piston to within inner piston region.

13. The forming machine recited in claim 12 wherein said primary piston head having greater outside diameter than said primary piston shaft means,

said primary stopping means constituting a gas cushion region confined in said chamber cylinder means surrounding said primary piston shaft means between said shaft closure means and the underhead surface of said primary piston head means and isolated from communication with said primary pressure gas whereby outward stroking motion of said primary shaft means from said primary chamber means causes compression of said gas cushion region and pressure buildup on said underhead surface of primary piston head means and through said pressure buildup limiting said outward motion and preventing disabling impact between said shaft closure means and said primary piston head and whereby first tooling member motion from stroke position is terminated at a limiting rest position in which the thrusts exerted on said primary piston head means and inner piston means by said primary pressure gas and said gas cushion are in equilibrium,

said reset means dependent upon said gas cushion whereby upon depressurization of the engaged surfaces of inner piston and head closure the thrust of said primary pressure gas acting axially on said inner piston means is reduced to less than the force of said gas cushion acting on the underhead surface of primary piston head means and whereby upon release of said hydraulic fluid from said inner piston region said thrust difference holds inner piston means engaged against head closure means and causes said primary piston means to retract into said primary chamber means thereby moving said first tooling member from limiting rest position to stroke position.

14. The forming machine recited in claim 1 wherein said secondary chamber means having chamber closure means at one end and a piston entrance at its other end, secondary piston means adapted for sealed reciprocating motion into and out from said secondary chamber means through said piston entrance,

5 a piston region confined within said secondary chamber means by the interior end of secondary piston means, said fluid control means adapted to deliver hydraulic fluid into said piston region only in response to operator controlled signal whereby said secondary piston means is moved out from said secondary chamber means and whereby said second tooling member is moved in direction toward said first tooling member to forming position,

10 said fluid control means adapted to maintain hydraulic fluid in said piston region whereby said secondary piston means is held in position extended from said secondary chamber means and whereby said second tooling member is maintained at forming position until said first tooling member strikes a single forming blow against said second tooling member thereby imparting motion to said second tooling member in direction away from said first tooling member and inducing a hydraulic pressure buildup in said piston region,

15 said fluid control means adapted to yield to said pressure buildup and thereby permit said secondary piston means to displace hydraulic fluid in piston region and to move into said secondary chamber means whereby said motion imparted to said second tooling member is sustained following a single forming blow.

20 25 30 35 40 45 50 55 60 65 15. The forming machine recited in claim 14 wherein said secondary stopping means operating after a forming blow at the end of secondary piston means travel into said secondary chamber means through close clearance male-female engagement between said secondary piston and the interior surface of said secondary chamber means whereby piston region hydraulic fluid metering from between piston and chamber closure creates a pressure force to stop the motion of secondary piston and said second tooling member and whereby said fluid acts as a cushioning medium to prevent damage to said piston and chamber closure means.

16. The forming machine recited in claim 14 wherein said fluid control means comprising valve piston means disposed aligned with and facing said secondary piston means within said secondary chamber means, valve piston adapted for reciprocating motion between said chamber closure means and an annular valve seat surface in the interior wall of said secondary chamber,

50 55 60 65 70 75 80 85 90 95 said secondary stopping means adapted to operate after a forming blow at the end of secondary piston's travel into said secondary chamber means through close clearance male-female engagement between said secondary piston means and valve piston means whereby piston region hydraulic fluid metering from between said secondary and valve piston means creates a pressure force to stop the motion of secondary piston and said second tooling member and whereby said piston region fluid acts as a cushioning medium to prevent damage to said secondary piston and valve piston means.

17. The forming machine recited in claim 14 wherein said fluid control means comprising valve piston means having a valve face communicable with hydraulic fluid in said piston region, said valve piston means disposed having reciprocating motion enabling said valve face to move against an annular valve seat surface in the interior wall of said secondary chamber means and adapted thereby to isolate said piston region from a low

pressure reservoir arranged with said secondary chamber means, valve spring means adapted to urge said valve piston means toward said valve seat surface whereby said valve piston means is held seated at all times against the force of piston region hydraulic pressure acting on said valve face except while said hydraulic pressure in said piston region over-balances the force of said valve spring, and whereby said valve piston means when seated 10 contains said fluid in said piston region from flowing into said low pressure reservoir and thereby maintains said second tooling member at forming position until a forming blow and whereby second tooling member motion induced by a forming blow 15 continues and is sustained as long as secondary piston displacement into said piston region produces sufficient hydraulic pressure to hold said valve piston means unseated or until said secondary stopping means halts said motion. 20

18. The forming machine recited in claim 14 wherein said fluid control means comprising gas pressurized hydraulic accumulator means,

communication between said accumulator hydraulic fluid and fluid in piston region of said secondary chamber being controlled by check valve means and separately by bypass valve means, 25 said check valve means disposed to permit fluid flow from said piston region into said accumulator means while preventing reverse flow from said accumulator means into said piston region, 30 said bypass valve adapted to open only in response to operator controlled signal and thereby deliver pressurized accumulator fluid into piston region, moving secondary piston means out from said secondary chamber means and said second tooling member to forming position whereupon said bypass valve is adapted to reclose, 35 said accumulator means adapted to yield and receive fluid through said check valve means from said piston region when a forming blow induces a pressure buildup in said piston region exceeding said accumulator gas pressure, whereby said secondary piston means is permitted to move into said secondary chamber means displacing fluid and second tooling member motion is thereby sustained following a forming blow. 40

19. The forming machine recited in claim 18 wherein said accumulator means integrally arranged in said secondary chamber means comprising annular piston means disposed having sealed reciprocating motion in an annular space isolated within said chamber means surrounding piston region, 50

said accumulator piston means disposed sealingly 55 segregating said accumulator pressure gas from accumulator hydraulic fluid within said annular space,

said check valve means comprising annular check plate means disposed with seating motion over port means which open from said piston region into said accumulator hydraulic region whereby flow from said accumulator region into said ports causes said check plate to seat and cover said ports thereby rendering said flow self-restrictive and whereas 60 flow out from said ports into accumulator region 65 causes said check plate to unseat and open passage for said fluid.

20. The forming machine recited in claim 18 wherein said check valve means comprising valve piston means having a valve face communicable with hydraulic fluid in said piston region, said valve piston means disposed having reciprocating motion enabling said valve face to move against an annular valve seat surface in the interior wall of said secondary chamber means,

said accumulator means integrally arranged in said secondary chamber means and comprising annular shaped accumulator piston means communicable with hydraulic fluid in an accumulator region which surrounds said piston region, said accumulator piston means disposed surrounding and in sealed reciprocating contact with said valve piston means,

said valve piston means and said accumulator piston means together confining and being together acted upon by accumulator pressure gas which urges said accumulator and valve piston means against hydraulic fluid of said piston and accumulator regions and whereby said valve piston means is further urged by said accumulator pressure gas to seat against said annular valve seat surface thereby checking surrounding hydraulic fluid pressurized by said accumulator piston means in said accumulator region from flowing into said piston region, said valve piston means disposed to move away from its annular valve seat surface while a forming blow induces a pressure buildup in said piston region exceeding said accumulator gas pressure, whereby piston region fluid is permitted to flow into said surrounding accumulator hydraulic region displacing said accumulator piston means and whereby said secondary piston means is permitted to move into said secondary chamber means and said second tooling member motion is thereby sustained following a forming blow.

21. The forming machine recited in claim 14 wherein said fluid control means comprising valve piston means having a valve face communicable with hydraulic fluid in said piston region,

said valve piston means disposed having reciprocating motion which enables said valve face to move against an annular valve seat surface in the interior wall of said secondary chamber means and adapted thereby to isolate said piston region from a low pressure reservoir arranged with said secondary chamber means,

valve control fluid confined by said valve piston means in said secondary chamber means and isolated from said piston region and said low pressure reservoir,

said valve control fluid adapted to exert a force which holds said valve piston means seated against the force of piston region hydraulic pressure acting on said valve face whereby fluid delivered into said piston region in response to operator controlled signal is contained and directed by said valve piston means to move said second tooling member to forming position,

said valve control fluid being controlled in such manner that the seating force exerted by said valve control fluid on said valve piston means decreases rapidly when a single forming blow is struck against said second tooling member whereby resulting secondary piston displacement into said piston region induces and is only resisted by decreased hydraulic

pressure in said piston region necessary to overbalance said decreased valve control fluid force and thereby hold said valve piston means unseated permitting hydraulic fluid to displace past said valve seat surface from said piston region into said low pressure reservoir and whereby second tooling member motion following a forming blow, being resisted by reduced piston region pressure, continues and is sustained until halted by said secondary stopping means.

22. The forming machine recited in claim 21 wherein secondary piston head means in rigid attachment to secondary piston shaft means within said secondary chamber means and disposed in sealed reciprocating contact with chamber cylinder means, said piston region confined in said secondary chamber means by the end face of said secondary piston head means, said secondary piston head means having a larger outside diameter than said secondary piston shaft means, chamber

secondary pressure gas confined in said secondary chamber means and disposed communicable within said chamber cylinder means and around said secondary piston shaft means between the underhead surface of said secondary piston head means and said piston entrance means,

said secondary pressure gas exerting a force on the underhead surface of said secondary piston head means which urges said secondary piston head and shaft means to displace into said piston region, said valve control fluid adapted to hold said valve piston means seated while hydraulic fluid is delivered into said piston region moving said secondary piston shaft means out from said secondary chamber means against the force of said secondary pressure gas on the underhead surface of said secondary piston head means and thereby moving said second tooling member to forming position,

said valve control fluid controlled in such manner that the valve seating force exerted on said valve piston means rapidly decreases when a forming blow is struck whereby resulting secondary piston shaft displacement into said piston region induces reduced hydraulic pressure to unseat said valve piston means and whereby said reduced hydraulic pressure in said piston region produces a reversal of the net force of said secondary pressure gas and said piston region fluid acting on said secondary piston head means and whereby said net force following a forming blow urges said secondary piston shaft means into said secondary chamber means and thereby acts to sustain second tooling member motion induced by a forming blow until said motion is halted by said secondary stopping means.

23. The forming machine recited in claim 14 wherein said fluid control means comprising valve piston means having a valve face communicable with hydraulic fluid in said piston region,

said valve piston means disposed having reciprocating motion enabling said valve face to move against an annular valve seat surface in the interior wall of said secondary chamber means whereby a part of the area of said valve face is isolated from communication with said hydraulic fluid in said piston region,

valve spring means disposed urging said valve piston means toward said valve seat surface,

hydraulic venting means adapted to reduce the hydraulic pressure on said isolated valve face area while said valve piston means is seated, thereby reducing the force of piston region pressure acting to unseat said valve piston means to a level less than the force of said valve spring means and thereby enabling said valve spring means to maintain said valve piston means seated whereby fluid delivered into said piston region in response to operator controlled signal is contained and directed by said valve piston means to move said second tooling member to forming position,

and whereby the impact of a forming blow causes hydraulic pressure in said piston region to increase to a level overbalancing the force of said valve spring means and thereby causes said valve piston means to unseat releasing said piston region fluid over the entire area of said valve face ($ar_{5x} - ar_{5v}$) and whereby, continuing to overbalance the force of said valve spring means, said hydraulic pressure in said piston region drops as a result of the increase in valve face area over which said fluid is released to act and whereby said hydraulic fluid at reduced pressure displaces said valve piston means away from its valve seat surface as said secondary piston means displaces into said piston region following a forming blow and whereby second tooling member motion continues and is sustained following a forming blow until halted by said secondary stopping means.

24. The forming machine recited in claim 23 wherein said valve spring means comprising valve spring pressure gas confined in said secondary chamber means and sealingly isolated from said piston region fluid by said valve piston means,

said valve spring pressure gas confined in such manner as to act on said valve piston means over a pressure area ($ar_{5x} - ar_{5v}$) and thereby urge said valve piston means to reciprocate towards said valve seat surface.

25. The forming machine recited in claim 23 wherein said secondary chamber means integrally connected with and contained in said second tooling member, said secondary piston means disposed on the far side of said second tooling member from said first tooling member and adapted having sealed reciprocating entry into said second tooling member on said far side and therein disposed confining said piston region,

the portion of said secondary piston means disposed outside said second tooling member being secured with the machine foundation whereby secondary piston displacement into and out from said piston region results as said second tooling member moves in direction respectively away from and toward said first tooling member,

said valve piston means being a ring shaped member disposed within said second tooling member surrounding the space into which said secondary piston means is received, said valve piston means disposed having reciprocating motion in the direction of said common axis and oriented to move in direction away from said first tooling member when closing against its valve seat surface.

26. The forming machine recited in claim 23 wherein

secondary piston head means in rigid attachment to secondary piston shaft means within said secondary chamber means and disposed in sealed reciprocating contact within chamber cylinder means,
 said piston region confined in said secondary chamber means by the end face of said secondary piston head means,
 said secondary piston head means having a larger outside diameter than said secondary piston shaft means,
 secondary pressure gas confined in said secondary chamber means and disposed communicable within said means chamber cylinder and around said secondary piston shaft means between the underhead surface of said secondary piston head means and said piston entrance,
 said secondary pressure gas exerting a force on the underhead surface of said secondary piston head means which urges said secondary piston head and shaft means to displace into said piston region,
 said valve spring means adapted with the aid of said hydraulic venting means to hold said valve piston means seated while hydraulic fluid is delivered into said piston region moving said secondary piston shaft means out from said secondary chamber means against the force of said secondary pressure gas on the underhead surface of said secondary piston head means and thereby moving said second tooling member to forming position,
 said valve piston means adapted to unseat when a forming blow induces a pressure increase in said piston region whereby piston region fluid is released over the entire area of said valve face ($ar_{5z}-ar_{5v}$) which in turn results in a decrease in piston region hydraulic pressure producing a reversal of the net force of said secondary pressure gas and said piston region fluid acting on said secondary piston head means and whereby said net force following a forming blow urges said secondary piston shaft means into said secondary chamber means and thereby acts to sustain second tooling member motion induced by a forming blow until said motion is halted by said secondary stopping means.

27. The forming machine recited in claim 26 wherein

45

said valve spring means comprising valve spring pressure gas confined in said secondary chamber means and sealingly isolated from said piston region fluid by said valve piston means,
 said valve spring pressure gas confined in such manner as to act on said valve piston means over a pressure area ($ar_{5x}-ar_{5v}$) and thereby urge said valve piston means to reciprocate towards said valve seat surface,
 said valve spring pressure gas disposed connected in fluid communication through piping or other passage means with said secondary pressure gas acting on the underhead surface of said secondary piston head means,
 the area ratio of said underhead surface ($ar_{5z}-ar_{5T}$) to said end face surface (ar_{5U}) of said secondary piston head means being less than the area ratio of said valve pressure area ($ar_{5x}-ar_{5v}$) acted upon by said valve spring gas to the area of said valve face ($ar_{5w}-ar_{5v}$) exposed to piston region fluid when said valve face is seated whereby said secondary pressure gas induces insufficient piston region hydraulic pressure to unseat said valve piston means before a forming blow,
 the area ratio of said underhead surface ($ar_{5z}-ar_{5T}$) to said end face surface (ar_{5U}) of said secondary piston head means being greater than the area ratio of said valve pressure area ($ar_{5x}-ar_{5v}$) acted upon by said valve spring gas to the full area of said valve face ($ar_{5z}-ar_{5U}$) whereby, once said valve piston means has unseated after a forming blow, the hydraulic pressure in said piston region necessary to continue displacement of said valve piston means away from its seat produces a force on the end face of said secondary piston head means which is less than the force exerted by said secondary pressure gas on said underhead surface thereby producing a net force urging said secondary piston means into said secondary chamber means and sustaining second tooling member motion induced by a forming blow until said motion is halted by said secondary stopping means.
